UNITED STATES PATENT OFFICE.

EDMUND C. MORGAN, OF RICHMOND HILL, NEW YORK; OLIVE EUGENIE MORGAN
EXECUTRIX OF SAID EDMUND C. MORGAN, DECEASED.

MINING MACHINE.

Application filed October 12, 1917. Serial No. 196,294.

The object of this invention is to provide a machine of the class named which shall be of improved construction and more efficient, economical and convenient in operation than similar devices previously known. The invention is exemplified in the combination and arrangement of parts shown in the accompanying drawings and described in the following specification, and it is more particularly pointed out in the appended claims.

In the drawings—

Fig. 1 is a top plan view of one form of a mining machine embodying the present invention.

Fig. 2 is a side elevation of the machine shown in Fig. 1.

Figs. 3, 4 and 6 together constitute an enlarged side elevation of the machine shown in Figs. 1 and 2, with the drilling mechanism removed, each figure representing a portion of the machine.

Figs. 7, 8 and 5 together constitute a top plan view of the entire machine shown in Figs. 3, 4 and 6.

Figs. 9 and 10 together constitute a central vertical sectional view of the machine, a portion of the cutter being omitted.

Figs. 11 and 12 constitute a horizontal sectional view of the machine taken just below the supporting frame for the cutter.

Fig. 13 is a vertical sectional view on line 13, 13 of Fig. 9.

Fig. 14 is a vertical sectional view on line 14, 14 of Fig. 9.

Fig. 15 is a vertical sectional view on line 15, 15 of Fig. 9.

Fig. 16 is a vertical sectional view on line 16, 16 of Fig. 12.

Fig. 17 is a vertical sectional view on line 17, 17 of Fig. 12.

Fig. 18 is a vertical sectional view on line 18, 18 of Fig. 10.

Fig. 19 is a fragmentary vertical sectional view showing a gear construction used in connection with the invention.

Fig. 20 is a top plan view of the mechanism shown in Fig. 19.

Fig. 21 is a vertical sectional view on the line 21, 21 of Fig. 20.

Fig. 22 is a vertical sectional view on line 22, 22 of Fig. 20.

Fig. 23 is a horizontal sectional view on line 23, 23 of Fig. 19.

Fig. 24 constitutes a top plan view of the drill frame and associated mechanism.

Fig. 25 constitutes an elevational view of the parts shown in Fig. 24.

Fig. 26 constitutes a vertical sectional view on line 26—26 of Fig. 24.

Figs. 27 and 28 show details of construction, Fig. 27 being a section on line 27—27 of Fig. 28.

Fig. 29 is a perspective view showing a detail of construction.

Fig. 30 is a horizontal sectional view substantially on line 30—30 of Fig. 26.

Fig. 31 is a fragmentary side elevation with parts in section, showing the automatic strip for the drill.

Fig. 32 is a vertical sectional view on the line 32—32 of Fig. 31.

Fig. 33 is a vertical sectional view on the line 33—33 of Fig. 32.

Fig. 34 is a horizontal sectional view on line 34—34 of Fig. 10.

Fig. 35 is a vertical sectional view corresponding to Fig. 34 but showing a modified form of construction.

Fig. 36 is an elevation of mechanism shown in Fig. 35.

Figs. 37 and 38 are plan and elevational views respectively of a modified form of jack for supporting the forward end of the supplementary track; and

Figs. 39, 40, 41, 42, 43 and 44 are diagrammatic views representing various steps in the operation of the machine.

This application is a continuation in part of my co-pending application, Serial No. 775,173, filed June 23, 1913, for apparatus for mining coal; the present application is also a continuation of my co-pending application, Serial No. 777,436, filed July 5, 1913, for apparatus for mining coal. The broader claims are set forth in Serial No. 775,173 and those next in scope in Serial No. 777,436, the claims in the present application being directed to improvements on the subject-matter of Serial Nos. 775,173 and 777,436.

The machine constituting the embodiment of the invention shown in the drawings, is carried upon a truck the frame of which is shown at 1, and the wheels 2 of which are arranged to travel on a track 3, which may be of the usual form employed in the entries and rooms of a mine. Supported on the frame of the truck at the rear end thereof, is a motor enclosed in a casing 4 and provided with a control box 5. The shaft 6 of the motor extends through a bearing 7 in the forward

wall of the casing 4 as shown in Fig. 9 and is provided with a bevelled pinion 8 rigidly connected with the shaft just outside the casing. The pinion 8 meshes with a bevelled gear 9 mounted to rotate on a short upright shaft 10 (Figs. 9 and 13), the lower end of the shaft being supported on a cross plate 11 and the upper end of the shaft being carried in a housing 12 which surrounds the 10 gearing and forms a support for the rear portion of the cutter frame. Extending forwardly from the housing 12 is a sleeve bearing 13 in which a shaft 14 is mounted to rotate. The shaft 14 has rigidly secured thereto a pinion 15 which meshes with a gear 16 rigid with the gear 9 but having the teeth arranged to project upwardly instead of downwardly. The housing 12, as will be understood from Figs. 7, 9, 13, 14 and 15, is provided at its base with an arcuate flange 17 which is held by a correspondingly shaped member 18 (Figs 7 and 9) which constitutes a slideway or turntable in which the housing 12 may rotate about the axis of the shaft 10 20 as a center. The member 18 is secured to the truck frame by lag screws 19. The flange 17 rests upon and is supported by a circular track 20 (see also Fig. 13) which is carried by the truck frame. This arrangement permits 25 the shaft 14 to be swung horizontally about the axis of the upright shaft 10 as a center without disturbing the driving connection between the shaft and the motor.

A cutter supporting frame comprising angle bars 21 (Fig. 13) supports a cutter at the forward end of the machine, as will be described, and the rear ends of the angle bars 21 are pivotally mounted on a bolt or pin 22 which extends through the housing 12, as shown in Figs. 7 and 9, and is provided with a head 23 and a nut 24 for holding it in place. The angle bars 21 are thus permitted to swing vertically about the bolt 22 as a horizontal axis, and also to swing laterally with the 45 housing 12 about the shaft 10 as an upright axis. The angle bars 21 are connected by a cross piece 25 (Figs. 7 and 9) which is provided with a bearing 26 in which a shaft 27 is rotatably mounted. The shaft 27 is provided with a clutch member 28 fixed thereto in the rear of the cross bar 25 and in position to mesh with a clutch 29 carried on the forward end of the shaft 14 and splined to the end of the shaft so that it will slide longitudinally thereon into and out of mesh with the clutch member 28. A lever 30 is provided for operating the clutch 29. The clutch members 28 and 29 are arranged to mesh with one another when the angle bars 21 are in 55 their lowermost position, and it is apparent that the clutch must be disconnected before the cutter frame, comprising the angle bars 21, can be raised, because the sleeve 13 in which the shaft 14 is journalled, is rigid with

the housing 12 and has no vertical movement. 65

As shown in Figs. 4, 8 and 10, the angle bars 21 are connected at their forward ends by a channel plate 31 which is secured to the upright webs of the angle bars 21 by rivets 70 32 and which has laterally extending portions 33 secured to the horizontal flanges of the angle bars 21 by rivets 34. The plate comprising the portions 31 and 33, is provided with a reinforcing flange 35 and also with an under-hanging circular rib 36 which engages the forward arcuate edge portion 37 of a plate 38 arranged to rest on the forward end of the truck frame and forming a supporting track on which the cutter frame may be 80 swung laterally. Set screws 39 provided with hand-wheels 40 are carried by the plates 33 to engage the plate 38 and clamp the cutter frame to its supporting plate to prevent lateral swinging movement when desired. The 85 forward end of the shaft 27 is journalled in a bearing 41 mounted on the upper surface of the plate 31 and a bevelled pinion 42 is secured to the shaft in front of the bearing. A bracket 43 projects forwardly from the reinforcing web 35 and supports at its front end an upright sleeve 44. A second sleeve 45 is journalled in the sleeve 44 and is rigidly secured at its upper end to a plate 46 which rests upon the upper end of the sleeve 44, 90 the sleeve 44 being provided with a horizontally arranged flange 47 for supporting the plate 46. The plate 46, as shown in Fig. 34, is provided with a series of openings 48 for receiving a pin 49 mounted to slide in an 100 opening in the flange 47, and provided with a coil spring 50 which normally presses the pin upwardly into the openings 48. A housing 51 for the spring 50 is carried by the flange 47 and an operating rod 52 for the pin 49 extends through the housing and is provided with a handle 53 by means of which the pin may be withdrawn from the openings in the plate 46. A stop 54 is carried by the housing 51 against which the handle 53 may 110 be caused to bear to hold the pin 49 in retracted position.

The lower end of the sleeve 45 carries a cutter bar 55 on the edges of which are slidably mounted guides 56 for a cutter chain 57, 115 provided with cutting bits 58 which may be of usual construction. The cutter chain 57 is driven by a sprocket wheel 59 secured to the lower end of an upright shaft 60 journalled to rotate in the sleeve 45. The upper end of 120 the shaft 60 carries a bevelled gear 61 arranged to mesh with the bevelled pinion 42 secured to the end of the shaft 27. At the forward end of the cutter bar 55 the guides 56 are connected by a head 62 which forms an 125 arcuate guide for the front end of the cutter chain 57, as shown in Fig. 5. The head 62 is connected with a cross bar 63, carried at the

front end of the cutter bar 55, by means of a screw 64 and lock nuts 65. This arrangement permits longitudinal adjustment of the head 62 and the guides 56 along the cutter bar 55 for regulating the tension in the cutter chain 57. It will be seen that the cutter bar 55 and its cutter chain may be swung laterally about the shaft 60 as an axis and held in its various lateral positions by the pin 49 and that the chain 47 will be driven in any of these positions by the motor mounted on the rear of the machine, through the shaft 27 and associated gearing.

The modified construction shown in Figs. 35 and 36 provides power mechanism for rotating the cutter bar 55 about its upright axis and is a substitute mechanism for the holding pin 49. In the modified construction the sleeve 45 is provided at its upper end with a worm wheel 66 which meshes with a worm 67 mounted in bearings 68 carries on the sleeve 44. The worm 67 carried a second worm wheel 69 which is driven by a worm 70 mounted on the shaft 71 of an electric motor 72 supported on a bracket 73 carried by the sleeve 44. By this mechanism the sleeve 45 and the cutter bar 55 may be swung laterally by the operation of the motor 72, and the cutter bar will be held in its various adjusted positions by the worm gearing by means of which it is driven.

The main drive shaft 6 extends forwardly from the motor (Fig. 9) through a bearing 74 supported on the cross bar 11, and to a bearing 75 in the front part of the machine as shown in Figs. 10 and 18. A shaft 76 extends across the main frame 1 of the truck, adjacent the forward end of the shaft 6 and supports a sleeve 77 loosely mounted thereon and journalled in a bearing 78 formed integral with a web plate 79 which forms a part of the main frame of the truck, as shown also in Fig. 17. The upper half of the bearing 78 is formed by a cap 80 held in place by lag screws 81 and on which the bearing 75 for the shaft 6 is mounted. The sleeve 77 carries at one end a segmental bracket 82 provided with gear teeth 83 arranged to mesh with a worm 84 rigidly secured to a shaft 85 (see also Fig. 12) which is journalled in bearings 86 and 87 mounted on the web plate 79. A worm wheel 88 is rigidly connected to the end of the shaft 85 opposite the worm 84 and is driven by a worm 89, as shown best in Fig. 17. The worm 89 is rigidly carried by a shaft 90 mounted in bearings 91 and 92 and carrying a friction cone 93 at its inner end. The cone 93 is arranged to mesh with a pair of friction cones 94 and 95 splined to the shaft 6, as shown in Fig. 12, and moved in unison by a yoke 96, so that either of the friction cones 94 or 95 may be caused to drive the shaft 90 and thus rotate the shaft in either direction at the will of the operator. The yoke 96 is shifted by an arm 97 carried

on a rod 98 (Fig. 4) which may be oscillated by means of a link 99 and lever 100 (Fig. 3), the lever being mounted on the motor frame at the rear of the machine.

The sleeve 77 has rigidly connected therewith a pair of arms 101 shown best in Figs. 10 and 18. These arms are connected at their forward ends by a sleeve 102 which is journalled on a pin 103 carried by downwardly projecting lugs 104 secured to the under surface of the plate 38 on which the forward end of the cutter frame rests and on which it is arranged to slide laterally as previously explained.

When the friction cone 93 is driven by the shaft 6 through its cooperating cones 94 or 95, the sleeve 77 will be shifted on its supporting shaft 76 through the two sets of worm gearing by which it is driven from the shaft 90, and the arms 101 will therefore be tilted upwardly or downwardly, depending on the direction of rotation imparted to the friction cone 93. Because of the two worm gears in the driving train for the sleeve 77, a comparatively slow and powerful movement is imparted to the two arms 101 in order to properly handle the weight of the cutter bar and associated parts. Because of this worm gearing, the cutter bar will be maintained in any position of vertical adjustment to which it is shifted. As previously stated, the clutch connection between the drive shaft 27 for the cutter head must be disconnected before the mechanism is operated to raise the cutter frame above its lowermost position.

During the operation of the machine it is usually desirable to support the truck beyond the end of the mining track 3, and for this reason a supplemental track consisting of a pair of rails 105 is supported beneath the frame of the truck. The rails 105 are connected by cross bars 106 and are arranged to slide longitudinally in a pair of shoes 107 adjustably connected with the truck frame by swinging links 108 and 109, as shown in Figs. 3, 4, 10, 13 and 18. The links 108 are rigidly connected with the shaft 76 which is journalled for rotation in the side bars of the truck frame 1, as shown in Fig. 18, and each of the links 108 is provided with a sleeve 110 which surrounds the shaft. One of the sleeves 110 has rigidly secured thereto a gear segment 111 provided with teeth 112 meshing with a worm 113 rigidly connected with a shaft 114 journalled at one side of the truck frame in bearings 115, 116 and 117, as shown in Figs. 11 and 12 of the drawings. The end of the shaft 114 adjacent the rear of the machine is provided with a worm 118 which meshes with a gear segment 119, (Fig. 13) carried by one of a pair of sleeves 120 to which the links 109 are secured. The sleeves 120 are rigidly secured to a shaft 121 journalled in the rear portion of the side bars of the truck frame 1. The shaft 114 is driven

by a worm wheel 122 secured to the shaft near the central portion thereof and which meshes with a worm 123 which may be rotated in either direction and at different speeds by mechanism to be described. It is apparent that rotation of the shaft 114 will swing the links 108 and 109 so as to raise or lower the supplemental track and thus move it into or out of engagement with the surface over which the truck is supported. The track may be slid longitudinally in the shoes 107 to change its position with relation to the mining machine. Mechanism for sliding the track will be presently described.

Extending transversely of the truck frame, near the middle thereof, is a main cross shaft 125 which is driven from the motor shaft 6 by mechanism best shown in Figs. 19 to 23 inclusive. Also journalled transversely of the truck frame on opposite sides of the shaft 125, as shown in Figs. 9 and 10, are two shafts 126 and 127 which are provided with worm wheels 128 and 129, respectively, meshing with worms 130 and 131 rigidly carried by the motor shaft 6. The shaft 126, as shown in Fig. 7, does not extend entirely across the truck frame but only a sufficient distance to carry its worm wheel 128 into position to mesh with the worm 130. The worms 130 and 131 are provided with right and left hand teeth respectively, so that the shafts 126 and 127 are driven in opposite directions. These shafts are provided with gears 132 and 133 respectively which are loosely mounted upon the shafts but which may be secured thereto by clutches 134 and 135. These clutches are connected by links 136 and 137 to arms 138 and 139 which are carried by a shaft 140 and extend in opposite directions therefrom, as shown in Figs. 11, and 12. The shaft 140 is provided with an operating handle 141 by which it may be oscillated about its axis to operate the clutches, and it is apparent that but a single clutch can be thrown into engagement with its respective pinion at one time, since one of the clutches is withdrawn at the same time that the other is thrown in. The pinions 132 and 133 mesh with teeth on the periphery of a spur gear 142 which is loosely mounted on the shaft 125. A series of three stud shafts, 143, are journalled in the gear 142 and are provided with pinions 144 and 145 on the opposite ends thereof. A second series of stud shafts 146 are journalled in the gear 142 and alternate with the shafts 143. The shafts 146 have gears 147 and 148 on their opposite ends. A stationary frame member 150 is provided with bearing openings for the shafts 125, 126 and 127 and carries internal gear teeth 151 and external gear teeth 152, in position to mesh with the pinions 147 and 148 respectively. A spur gear 153 is loosely journalled on the shaft 125 in position to mesh with the pinions 145, and a frame 154 is loosely journalled on the shaft 125 and

has internal gear teeth 155 arranged to mesh with the teeth of the pinions 148. The pinions on the opposite ends of the shafts 143 differ slightly in size, so that the pinions on one end of the shafts have more teeth than the pinions on the opposite ends thereof. The same thing is true of the pinions on the opposite ends of the shafts 146, except that the difference between the numbers of teeth on opposite ends of the shaft is greater in the case of one of the sets of shafts than it is in the other. It is apparent that rotation of the gear 142 will produce a differential drive between the fixed member 150 and the rotatable members 153 and 154, and that a slow and powerful movement will be imparted to the rotary members. It is also apparent that the rates of rotation of the members 153 and 154 will differ from one another due to the fact that they are driven by gears having different gear ratios. Since the shafts 126 and 127 rotate in opposite directions, and since the gear 142 can be driven by either of these shafts, it is seen that the members 153 and 154 can also be rotated in either direction. The shaft 125 is provided with a dovetailed sliding clutch 156, one end of which is arranged to mesh with clutch teeth on the face of the gear 153, and the other end of which is arranged to mesh with clutch teeth 157 connected with the frame 154. The clutch 156 is provided with rollers 158 which slide in a ring 159 by means of which the clutch may be shifted to mesh with either of the rotatable members 153 or 154, or may be set in neutral position. Thus it is possible to impart movement in either direction at two different rates of speed to the shaft 125. The clutch 156 is operated by a rod 160 having arms 161 (Fig. 16) which are connected with the ring 159. The rod 160 extends to a position adjacent the rear of the machine and is provided with an operating handle 162.

The shaft 125 carries at its outer ends (as shown in Figs. 11, 12 and 16) a pair of winding drums 163 and 164 which have cables 165 and 166 respectively wound thereon. The drums are provided with clutches 167 and 168 by means of which they are secured to the shaft 125 to be driven thereby. The cables 165 and 166 pass over guide pulleys 169 and 170 at the forward end of the machine and are provided with loops 171 and 172 by means of which the ends of the cables may be secured to suitable anchors within the mine rooms or entries so that the mining machine may be advanced by winding the cables upon their respective drums.

The shaft 125 is provided with a second pair of drums 173 and 174 which are formed integral with one another and which may be connected to the shaft 125 by a clutch 175. The clutch 175 is operated by arms 176 (Fig. 16) secured to a rod 177 which extends to the rear of the machine and is provided with an

operating handle 178 (Fig. 3). Cables 179 and 180 are wound in opposite directions on the drums 173 and 174 respectively, and the ends of the cables 179 and 180 are secured to opposite ends of the supplemental track consisting of the rails 105 and cross pieces 106. When the drums 173 and 174 are rotated, the supplemental track will be shifted relative to the machine frame if the frame is held stationary, or the machine itself will be shifted on the track when the track is anchored to the ground and the machine is supported thereon. The direction of the relative movement of the track and the machine will depend upon the direction of rotation of the two drums, and this, as previously stated, can be regulated by the driving mechanism for the main cross shaft 125.

In order to drive the machine upon the mine track 3, a connection is provided between the motor shaft 6 and the truck axles. This connection consists of a pair of worms 181 and 182 (Figs. 9 and 10) which are loosely mounted on the shaft 6 and may be secured thereto by clutches 183 and 184 respectively. These clutches are connected by links 185 and 186 to a cross bar 187 carried on a shaft 188 which is connected by an arm 189 (Fig. 3) and a link 190 to an operating lever 191 at the rear of the machine. The worms 181 and 182 mesh with worm wheels 192 and 193 respectively, which are secured to the axles 194 and 195 of the truck frame. The direction of movement of the truck is controlled by reversing the direction of rotation of the driving motor. It may be noted that although the motor is reversible, it is not practical to operate it in a reverse direction during the time that the cutter chain is being operated, for the reason that the cutter chain will perform its cutting function only when it is driven in one direction. For this reason it is desirable to provide reversing mechanism for the shaft 125 as previously described, since it is sometimes necessary to reverse the direction of movement of this shaft during the operation of the cutter chain.

Runways or platforms 196 and 197 are supported on the truck frame adjacent the rear portion, to accommodate the operator, and as has been previously pointed out, the various control levers are located at the rear of the machine in position to be reached by an operator upon these platforms.

The supplemental track is provided with a rotary shaft 198, at its front end, which carries a pair of cam shaped jacks 199 provided with sockets 200 for receiving levers or crowbars by which the jacks may be swung into engagement with the surface of the mine floor and thus the front end of the track may be properly adjusted relative to the floor. Ratchet wheels 201 and pawls 202 are provided for holding the jacks in their adjusted positions. In place of cam jacks as described,

screw jacks 203, (as shown in Figs. 37 and 38) may be used. This arrangement will permit independent adjustment of the opposite sides of the supplemental track at its forward end.

The operation of the machine as thus far described will now be clear. When it is desired to perform an undercutting operation in a mine room or entry, the machine is run along the mine track 3 to a position adjacent the end of the chamber. If the machine is operating in a wide room (as indicated in Fig. 39) the cutter frame is then swung about the shaft 10 as an axis into position indicated at *a* in Fig. 39 of the drawing. This moves the cutter to one side of the machine so that the supplemental track may be run forward by the drums 173 and 174, the rails of the track sliding through the shoes 107. Sufficient space is left between the front end of the track and the wall of the mine chamber to permit the rear of the cutter chain to pass between the track and coal wall or face. The supplemental track is then swung by the links 108 and 109 downwardly until the weight of the machine is supported by the supplemental track. The height of the cutter bar 55 from the floor of the mine may be regulated within certain limits by the height to which the machine is raised above the supplemental tracks, through the adjustment of the links 108 and 109. The jacks 199 are used to properly regulate the height of the front end of the track while the rear end of the track is permitted to rest upon the cross ties of the mine track 3. By this adjustable means of the supplemental track, the cut may be made perfectly level or inclined downwardly or upwardly as desired. When the track has been properly located, it may be anchored in any suitable manner, such for instance, as jacks to the roof. The cutter chain may now be driven by the motor and the mining machine slid forwardly on the supplemental track by the cable 179 and its operating drum 173, to feed the cutter into the position indicated at *b* in Fig. 39 of the drawing. The forward feed could also be performed, if desired, by means of ropes 165 and 166 by securing their ends to suitable jacks anchored forward of the machine. During the forward movement the cutter bar 55 and the cutter frame comprising the angle bars 21, are locked rigidly together at the joint between them either by the locking pin 49, or if the modified form of construction shown in Figs. 35 and 36 is used, by the worm gearing forming a part of that construction, the cutter frame comprising the angle bars 21 and plate 33 being locked at any desired angularity with respect to the main body of the machine by means of the set screws 39. From the position *b* the cutter is swung about its upright axis into the position *c*. This lateral swinging of the cutter may be accomplished by carrying the rope 165 around a suitable pulley secured to a jack anchored near the left

hand rib of the mine chamber and fastening its looped end over a pin 205 connected to the cutter bar as shown in Fig. 4, and winding the cable on to its drum 164. The cable 166 would be used in the same manner in the reverse direction if it was desired to feed the cutter bar from left to right of the mine chamber. If this were done it should be understood that the cutting chain can easily be reversed to cut in the opposite direction to that shown in the drawings, if desired. During this lateral swinging the cutter chain continues to operate and thus forms the main part of the under cut. From position *c* the cutter is moved to position *d* by feeding the mining machine backwardly along its supplemental track by means of the rope 180 on drum 174. The end of the rope being fastened to the rear end of the supplemental track, thus returning it to its original position upon the main track of the mine room. This operation completes the undercut and since the drill holes for the blast are made during the time that the cutter is swung from one side 25 of the mine room to the other, as will be explained, the operation of the mining machine is complete when the cutter is brought back into position *d*. Attention is called here to the fact that all the blast holes for blasting down 30 the undercut coal are completed as soon as the undercut is made. By means of my combined mechanism the drilling is done without loss of time in the undercutting operation, and reversely, the undercutting is done without loss of time in the drilling operation. The supplemental track may now be returned to a position beneath the mining machine and lifted so that it will free the main track of the mine room. After the track has thus been 35 restored to position for transportation, the cutter frame is swung back to a central position, the clutch 29 is released and the cutter bar is raised by the arms 101 until it is in position to free the mine track. The machine 40 may now be run to another chamber where it can continue its operations while the material that has been undercut is blasted down and removed.

The mechanism for drilling the blast holes is shown in Figs. 1, 2, 24 to 32 inclusive, 43 and 44. This mechanism (as shown in Figs. 1 and 2) is bolted to the upper rear portion of the mining machine and may be easily removed when necessary. The drilling mechanism is mounted on a base plate 206 which is provided with a pair of upwardly projecting bearing rings 207, in which hollow trunnions 208 of a housing 209 are journalled. The housing 209 is split along line 210, as shown in Fig. 25, to allow access to the interior thereof, the parts being held together by bolts 211. A shaft 212 is journalled in the hollow trunnions 208 and carries a gear 213 which meshes with a pinion 214 driven by a motor 215 carried within the housing 209.

At each end of the housing 209 and beyond the trunnions 208, there is located a bearing box 216 which forms an integral continuation of the trunnions 208. Located within these bearing boxes are bevelled pinions 217 carried on the ends of the shaft 212 and arranged to mesh with bevelled pinions 218 connected with the upper end of a sleeve 219 journalled on a bearing pin 220, as shown in Figs. 25 and 26. Journalled on the pin 220 above and below the sleeve 219, are members 221 and 222 which are secured to a bar 223, the three members thus connected together constituting a supporting frame for one of the drills and its operating mechanism. A threaded feed screw 224 is journalled in the member 221 and is provided with a bevelled pinion 225 which meshes with the pinion 218. By this arrangement the guide bar 223 is provided with a universal joint connection which permits both vertical and lateral movement of the drill frame relative to the supporting plate 206, without disengaging the driving connection between the feed screw 214 and the drive shaft 212. A central guide bar 226 may be rigidly connected with the housing 209 to swing vertically with the housing in the bearing rings 207, since no lateral movement of the central drill is necessary. The two end guide bars 223 and the central guide bar 226 may be supported by a leaf spring 227 secured to the base plate 206 by bolts 228, and to a lug 229 fastened to the central guide bar 226. The entire housing 209 and the drills connected therewith may be swung vertically in the bearing rings 207 by a hand wheel 230 which engages the threads of a screw 231 passing loosely through an opening in an arm 232 connected with the housing 209 and pivoted at 233 to an arm 234 rigidly secured to the base plate 206. The outer drill bars 223 may be swung horizontally by the hand wheels 235 connected with threaded members 236 which are pivoted to the outer bars 223 and the inner bar 226 respectively, as shown in Fig. 24.

The drills 237 are held at their inner ends in short shafts 238 provided with sockets 239 for the reception of the drills. The outer ends of the drills 237 are freely supported in openings 240 passing through blocks 241 secured to the outer ends of the guide bars 223 and 226 by screws 242. The blocks 241 are also provided with journal bearings for the outer ends of the feed screws 224. The short shaft 238 is journalled in a split block 243 and carries a gear 244 rigidly secured to the shaft. The gear 244 meshes with a gear 245 also journalled in the split block 243 and having an elongated hub provided with a key 246 adapted to travel in a slot 247 which extends the entire length of the feed screw 224. By this arrangement the drill 237 is driven by the feed screw 224 independently of the position of the block 243 along the length 130

of the feed screw. The blocks 243 are supported from the guide bars 223 and 226 by a dovetailed connection best shown in Fig. 32. A housing 248 is secured to the front face of the block 243 by lag screws 249 and incloses a split nut comprising two parts 250 and 251 for engaging the threads on the feed screw 224, as best shown in Figs. 32 and 33. The blocks 250 and 251, which comprise the parts of the split nut, are mounted to slide vertically in the housing 248 and the lower block 250 has a shaft 252 journalled therein and provided with eccentric cams 253 at the outer ends thereof. Each of the cams 253 engages a link 254 which is pivotally connected at its opposite end to the upper block 251 of the split nut. It is apparent that rotation of the shaft 252 will move the blocks 250 and 251 toward and away from one another and into and out of engagement with the feed screw 224. One end of the shaft 252 carries a pinion 256 which is concentric with the shaft 252 and which is free to rotate thereon and which has a pin 257 projecting outwardly from its face. The pin 257 is connected by a coil spring 258 with a pin 259 fixedly secured to the housing 248. The inner face of the pinion 256 carries a segmental lug 260 which engages a similar lug 261 projecting from the cam 253, as best shown in Figs. 27 and 28. The tension of the spring 258 normally holds the lug 260 in the position shown in these figures, and the lug 261 contacts with the lug 260 when the cams 253 are moved slightly past their central lower position in a direction to bring the lug 261 into engagement with the lug 260. In this way the blocks 250 and 251 are normally held in engagement with the feed screw 224 and any tendency of the blocks to spread apart is counteracted by the contact between the lugs 260 and 261. As shown in Figs. 31 and 32, a cylindrical rack bar 262 is slidably mounted in a projection 263 connected with the housing 248 and meshes with the gear 256. The rack bar 262 normally extends outwardly from the front face of the housing 248 when the split nut engages the feed screw 224.

During the operation of the drill, the housing 248 and the split block 243 connected therewith, are fed forwardly along the guide bar 223 by the split nut, and this operation continues until the end of the rack 262 comes into contact with the block 241 at the end of the guide bar. When this occurs, further forward movement of the housing causes the rack to rotate the gear 256 in a counter-clockwise direction, as viewed in Figs. 31 and 32. This rotation of the gear 256 will move the projection 260 through a half-circle away from the projection 261 on the cam 253, and the position of the cam and the split nut controlled thereby will not be affected until a half-revolution of the gear 256 has been completed. Further rotation of the gear, how-

ever, will bring the pin 257 to which the spring 258 is connected, past the dead center at the lower side of the gear, and the spring will immediately complete the rotation of the gear and at the same time drive the rack 262 through its support 263 until it projects from the opposite side of the support an amount equal to the projection shown on the forward side of the support in Fig. 31. It is apparent from Fig. 28 that at the beginning of the rotation of the gear 256 by the spring 258, the projection 260 will engage the projection 261 but on the opposite side from that shown in this view, and that the rotation of the gear by the spring will bring the projection 261 to a vertical position above the shaft 262, and will also bring the cams 253 into position above the axis of the shaft. This will spread apart the blocks 250 and 251 and disengage them from the feed screw 224. In this way an instantaneous release of the drill from the feed screw is effected.

After the drill has been released from the feed screw, it may be returned to its original position by a drum and cable mechanism best shown in Fig. 30. This mechanism comprises a drum 265 on which a number of cables 266 are wound, the cables being directed over pulleys 267 and having their ends secured to pins 268 connected with the split blocks 243. The drum 265 is controlled by a clutch 269 operated by a lever 270 (Fig. 24) carried on a shaft 271 which projects through the housing 209. By throwing in the clutch 269 after the drills have ceased to feed forwardly, the cables 266 may be wound upon the drum and the drills will thus be simultaneously returned to their initial positions. As the drills are brought into the rearmost positions, the rear ends of the racks 262 will engage the rear portion of the frame and thus be moved forwardly to reset the gears 256 and to re-engage the split nuts with the feed screw 224, thus automatically setting the feeding device for a second operation. The motor for driving the drilling mechanism may be governed by a controller 272 mounted on the housing 209, as shown in Fig. 30.

The drilling operation is shown diagrammatically in Figs. 43 and 44 in which the positions of the drill frames are indicated by the reference letters *e*, *f* and *g*. It will be seen from Fig. 44 that the drill frame is inclined upwardly out of parallelism with the undercutter. It will be apparent that the mining machine cannot be moved upon its track while the drill is in operation in this position, and it is therefore desirable to perform the drilling operations while the undercutter is being shifted laterally. Ordinarily, the greater part of the undercutting operation is performed by this lateral shifting of the undercutter, and hence sufficient time is afforded for drilling the blast holes during this phase of the undercutting.

Where the undercutting is carried on in a narrow entry (as shown in Fig. 40) the operation differs from that indicated in Fig. 39. In this case in the first position *a* of the cutter, the bar 55 is set at an angle to the cutter support in order that the rear end of the bar may be positioned at one side of the supplemental track. The machine is then fed forward from the position *a* to the position *b*, then across to position *c*, and from this position the angle between the cutter bar and the supporting frame is shifted to bring the cutter into the position *d*. The machine is then fed backwardly upon its track to bring the cutter into the position shown at *e*, which completes the undercutting operation. Where this method of operation is employed, it is necessary to use the form of connection between the cutter bar and its supporting frame, shown in Figs. 35 and 36 of the drawing, in order that the power mechanism there shown may be employed for changing the angle between the cutter bar and its supporting frame.

Where it is desired to undercut at the side of a room or entry, the cutter is first placed in the position shown at *a*, in Figs. 41 and 42, from which position the cutter bar is fed around to *b* by the power feed shown in Figs. 35 and 36. The machine is then moved forwardly along its track to position *c*, from which position the cutter bar may be rotated relative to its supporting frame to bring the bar into the open chamber, cutting through the intervening material, or the machine may be moved backwardly and the cutter bar swung from beneath the undercut material through the kerf already formed.

It should be particularly noted that on account of the adjustable joint between the elongated cutter-bar and the elongated supplemental frame, the kerf-cutter may in some instances where the entry is narrow but with sufficient spaces between the mine track and the walls, be moved along such spaces. The main track may then be laid up close to the working face and after the mining machine has been transported to a position adjacent the working face, the kerf-cutter may be let down to occupy the space at one side of the main track between the latter and the adjacent mine wall. The machine may then be moved along the main track to secure rectilinear feeding movement of the kerf-cutter approximately longitudinally of itself while being held in adjusted relation to the supplemental frame. After the cutter has been fed laterally, its angular relation with the supplemental frame may be re-adjusted to secure further feeding movement, and finally the kerf-cutter may be retracted from the working face to the space on the opposite side of the track between the latter and the adjacent mine wall. It will thus be seen that when the entry is of sufficient width the supplemental track mechanism may be omitted

in some instances if desired, but when the entry is so narrow that the kerf-cutter cannot be moved along the spaces between the track and the adjacent mine walls, then the supplemental track of narrow gauge is particularly desirable to afford continued support for the mining machine while at the same time affording sufficient space at the lateral sides thereof for the advance and retraction of the kerf cutter, as illustrated in Fig. 40.

In view of the foregoing description of the various parts of the machine shown in the drawings it will be seen that the wheeled track guided truck is provided with a base 80 with a pivotal mounting thereon for a cutter bar, this mounting being pivoted about the vertical axis 10 shown in Fig. 7. A cutter bar is pivoted on this mounting to swing about the vertical axis 60 shown in Fig. 10 85 which is offset from the axis shown at 10 in Fig. 7. As shown in Fig. 2, the cutter bar may be disposed in a transverse plane beneath the top of the mine track 3 and also beneath the top of the supplemental track 105. The pivot 10 and the guiding mechanism shown at 37, 38 in Figs. 4 and 8 permit a wide lateral swinging movement of the mounting comprising the frame 21. It can therefore readily be seen by referring to Figs. 39 to 95 44, inclusive, that while the kerf-cutter is cutting at the floor level the cutter bar pivot 60 may occupy a position wholly at either side of not only the supplemental track 105, but also the main mine track 3. By means of the 100 pin 49, shown in Fig. 10, fitting in one of the holes 48, shown in Fig. 34, the cutter bar may be held with its longitudinal axis in the same vertical plane that includes the vertical axis 10. This is illustrated in Figs. 39 105 and 43 of the drawings. The aperture for this purpose is the central one shown in Fig. 34. In addition to this central aperture there is a plurality on each side of it arranged at equal angles so as to hold the cutter bar in 110 various adjusted positions illustrated in Figs. 40 to 42, inclusive.

The chain cutter travels in an orbit within which the pivot 60 of the cutter bar is disposed, as shown in Fig. 8. This upright 115 pivotal support which is carried on the main frame may be shifted laterally relatively to the main frame. That is to say, the upright axis 60 may be swung laterally relatively to the main frame on the upright axis 10 of 120 Fig. 7. The guiding mechanism shown at 37, 38 in Fig. 4 holds the pivot 60 in upright position. When the pin 49 is released from the holes the cutter bar is free to swing on the upright pivot 60 and such swinging may 125 be effected by movement of the truck along the track while the extreme forward end of the cutter bar abuts against the mine wall. This construction including the pin 49 affords the releasable connection operative to hold 130

the cutter bar in fixed relation to its pivot 60 or when released continued swinging of the pivot 60 may automatically cause relative movement between the cutter bar and the 5 mounting 21. In other words, the releasable connection between the cutter bar and its pivot enables the motor driven means to swing the frame 21 to bodily shift the pivot 60 and change the angular relation between 10 the cutter bar and the frame 21 while the tip or extreme outer end of the cutter bar remains substantially stationary.

Therefore, when desired, a sumping cut 15 may be made in a narrow entry, as illustrated in Fig. 40, by a rectilinear forward feeding movement while the kerf-cutter cuts at the mine floor level with the pivot 60 at one side of the mine track. Lateral swinging feeding movement may be effected to the position shown at *c*. Then the cutter may be 20 adjusted to the position shown at *d* and a rectilinear rearward feeding movement effected to the position shown at *e*.

Since the elongated chain cutter travels 25 in a closed loop it travels along an orbit having major and minor axes and when the cutter is in the position shown at *a* in Fig. 40 the major axis makes a less angle with the line of the track than is made by a line 30 connecting the end of the major axis remote from the vertical axis 10, with said vertical axis. That is to say, the cutter when in the position shown at *a* in Fig. 40 at the beginning of the sumping cut is disposed at an 35 acute angle to the arcuate cut at its juncture with the rib. At this time the cutter is disposable upon the bottom and wholly between the track and the rib. When the chain cutter is driven its cutting elements 58 are circu- 40 lated around the cutter bar and the kerf-cutter while at either side of the mine track may be reciprocated rectilinearly. When the overhanging arm is in its lower position, as shown in Fig. 2, a kerf may be cut at the 45 floor level in advance of the mine track and as illustrated in Figs. 39, 40 and 43.

I claim:

1. In combination, a mining machine having a main frame, an elongated cutter supporting frame carried by said main frame, an elongated cutter bar pivotally connected to said supporting frame, means for holding said supporting frame and cutter bar rigidly fixed to said main frame, means for advancing said main frame to cause said cutter bar to form a kerf in material to be mined, means for swinging said supporting frame with said cutter bar held rigid relative thereto to feed said cutter bar into said material, and means 55 for swinging said cutter bar relative to said supporting frame to feed said bar into said material.

2. In a mining machine, the combination with a main frame, of a cutting element pivot- 60 ally mounted on said main frame for swinging

movement relatively thereto on an upright axis, means for shifting the pivotal support of said cutting element laterally relatively to said main frame while maintaining said axis upright, means for holding said cutting element rigid relative to said main frame in its various positions to which it is shifted laterally, and means for swinging said cutting element laterally about its upright pivotal support in the various positions of said 70 support.

3. In combination, a mining machine comprising a main frame, a cutter supporting frame having one end thereof pivotally mounted at one end of said main frame, an 80 elongated cutter bar pivotally mounted on said supporting frame at the end thereof opposite the pivotal connection between said supporting frame and said main frame, means for swinging said supporting frame about its pivotal connection with said main frame to shift the position of said cutter bar relative to said main frame, means for holding said supporting frame rigidly relative to said main frame in its various adjusted positions, means for swinging said cutter bar about its connection with said supporting frame, means for holding said cutter bar rigid with said supporting frame in its various positions relative thereto, and means for 85 advancing said main frame, supporting frame and cutter bar in unison with one another.

4. In coal mining apparatus adapted to cut a kerf at the base of a mine wall in a narrow entry while supported and guided by the mine track during its cutting operation, the bottom line of the kerf being in a plane parallel with the plane of the top of the track but below it, the combination with a main frame, of truck wheels for supporting said main frame on a mine track, self-contained self-propelling mechanism for said truck wheels, an elongated cutting element pivotally mounted on said frame in position to 100 cause its bottom cutting line to be in a plane below the plane of the top of the mine track throughout its cutting operation, means for holding the cutting element at adjusted angles, said cutting element having a lateral bodily movement relatively to the main frame, and being adapted to assume positions at each side of the track rearwardly of the front end thereof when the lateral feeding movement is limited to less than four times the track gauge of the mine track, and means for operating said cutting element including lateral bodily feed thereof relatively to the main frame, and bodily feed thereof on both sides of the front end of the track 110 rearwardly of such front end to effect cutting along such low lines below the top of the mine track and at the sides of the front end thereof.

5. In a mining machine, an elongated cut- 115

ter frame, means for holding said frame in a fixed angular position, and for feeding said frame into material to be mined, means for swinging said frame about a point outside of said frame as an axis to feed said frame through said material into a different angular position, means for holding said frame fixed in said second angular position, and means for feeding said frame through said material while so held.

6. In a mining machine, the combination with a main frame, of a supplemental frame pivotally mounted on said main frame for lateral movement relatively thereto, an elongated cutting element pivotally mounted on said supplemental frame for lateral movement relatively thereto, means for holding said cutting element in fixed angular position relatively to said supplemental frame, means for holding said supplemental frame in fixed angular position relatively to said main frame, means for propelling said main frame to secure rectilinear feeding movement of said cutting element while said supplemental frame and said cutting element are held in such fixed angular positions, means for swinging said cutting element about its pivotal connection with said supplemental frame, and means for swinging said supplemental frame about its pivotal connection with said main frame to secure arcuate movement of said cutting element on a longer radius, and means for actuating said cutting element during such swinging movements.

7. In a coal mining machine adapted to cut a kerf the bottom of which is approximately in the plane of the mine floor in a narrow entry while the machine is supported and guided by the mine track during its cutting operation, the combination with a main frame, of wheels for supporting said main frame on a mine track, an overhanging arm mounted on said main frame with its outer end in position to swing horizontally across the end of the mine track, an elongated cutting element pivotally mounted on the outer end of said overhanging arm in position to swing horizontally, the range of horizontal movement of said overhanging arm on the main frame and the range of pivotal movement of said cutting element on the outer end of said overhanging arm being such as to permit the cutting element to be at one side of the mine track with its bottom line below the top of the track during its feeding in movement, and on the other side of the track with its bottom line below the top of the track during its feeding out movement, means for effecting reciprocation of the machine bodily on the mine track to effect feeding of the cutting element during a portion of its operation, means for swinging the overhanging arm laterally to effect the feeding of the cutting element during another portion of its operation, and means for locking the cutting

element at its pivot on the outer end of the overhanging arm in a plurality of positions.

8. In a mining machine, a main frame arranged to travel upon a track in a mine chamber, a supplemental track, a cutter bar supported from said main frame in a position adjacent the floor of said mine chamber, and means for raising and lowering said main frame on said supplemental track to shift said supplemental track into and out of contact with said mine floor, and to adjust the position of said cutter bar relative to said floor.

9. In a mining machine, the combination with a main frame, of an elongated supplemental frame carried by said main frame, an elongated cutting element connected with one end of said supplemental frame adjacent one end of said main frame in position to cut a horizontal kerf at the base of a mine wall, means for connecting the other end of said elongated supplemental frame with the other end of said main frame for vertical and lateral swinging movements relatively to said main frame, and means carried by said elongated supplemental frame for transmitting operating power to said cutting element.

10. In a mining machine, the combination with a main frame, of wheels for supporting said main frame on a mine track, a motor mounted on said main frame near one end thereof, a cutter-supporting frame pivotally mounted on said main frame adjacent said motor for lateral and upright swinging movements relatively to said main frame, an elongated kerf-cutter carried by said cutter-supporting frame and confined to a position in parallelism with the lateral movements of said cutter-supporting frame, and power transmission mechanism carried by said main frame and said cutter-supporting frame for transmitting power from said motor on said main frame to said kerf-cutter when the latter is in operating position.

11. In a mining machine, the combination with a main frame, of a support swivelled on said main frame for rotation about an upright axis at the rear portion of said main frame, a cutter-supporting frame connected to said support by a pivot on a horizontal axis at the rear portion of said main frame, a cutting element carried by said supporting frame at the forward end thereof in advance of said main frame, means for lifting said cutter-supporting frame and said cutting element to clear the track on which said main frame is mounted and to permit transportation over said track, and to lower the cutter-supporting frame and said cutting element into position for cutting a kerf the bottom of which is approximately in the plane of the floor on which said track is mounted, and means for operating said cutting element including lateral movement of said supporting

frame on the upright pivotal axis at the rear portion of the main frame while said supporting frame and cutting element are supported entirely by said main frame with the space between the forward end of said track and said cutting element free and unobstructed.

12. In a mining machine, a main frame having a horizontally extending drive shaft journaled therein, a gear housing swivelled 10 on said main frame for rotation about an upright axis, a pinion carried by said drive shaft, a gear mounted within said housing and meshing with said pinion, the axis of rotation of said gearing co-inciding with the 15 axis of rotation of said housing, a shaft journaled in said housing and having a pinion thereon meshing with said gear, a cutter supporting frame pivotally connected with said housing to swing vertically relative thereto, 20 a driven shaft carried by said cutter supporting frame, and means for operatively connecting said driven shaft with the shaft journaled in said housing.

13. In a mining machine, a main frame, a 25 cutter supporting frame pivotally mounted on said main frame and arranged to swing about upright and horizontal axes thereon, driving mechanism carried by said main frame, a shaft arranged to be driven by said 30 driving mechanism and movable with said cutter supporting frame about one of the axes therof, but fixed with relation to the movement of said cutter supporting frame about the other axis, a drive shaft carried by said 35 cutter supporting frame, and a clutch for operatively connecting said shafts and for disconnecting said shafts to permit movement of said cutter supporting frame about one of its pivotal connections with said main 40 frame.

14. In a mining machine, the combination 45 with a main frame, of a motor carried by said main frame, propelling mechanism for said main frame, a shaft driven by said motor and having operative connections with said propelling mechanism, a cutter supporting frame pivotally mounted on said main frame to swing up and down on a horizontal axis relatively to said main frame, a shaft mounted on 50 said cutter supporting frame, means for adjusting the elevation of said cutter supporting frame to hold the same at sufficient elevation when transporting the machine and to let down the same to operative position, and 55 means for connecting the shaft on the cutter supporting frame to the motor driven shaft when said cutter supporting frame is let down into operative position.

15. In a mining machine, the combination 60 with a main frame, of a supplemental frame pivotally mounted at the rear portion of said main frame to swing laterally relatively thereto on an upright axis, a support at the forward portion of said main frame for the forward portion of said supplemental frame,

said supplemental frame being movable laterally on said forward support while occupying an approximately horizontal position, a cutting element carried by said supplemental frame in position to cut a horizontal kerf when said supplemental frame is in a horizontal position, means for operating said cutting element to cut such kerf, and means for lifting and lowering said support together with said supplemental frame and 75 said cutting element, on a horizontal pivotal axis at the rear portion of said main frame to enable the machine to be freely transported.

16. In a mining machine, a main frame, a 80 supplemental frame pivotally mounted at one end thereof on said main frame, a chain kerf cutter carried by said supplemental frame at the end thereof opposite its pivotal connection with said main frame, a support carried 85 by said main frame on which said supplemental frame is free to slide laterally, an arm connected with said support for adjusting said support vertically relative to said main frame, a pivotal connection between 90 said arm and said main frame, and means for swinging said arm about said connection to raise and lower said supplemental frame and kerf cutter carried thereby, and means for operating said kerf-cutter. 95

17. In a mining machine, a main frame, a cutter supporting frame mounted on said main frame and movable vertically relatively thereto, a shaft carried by said main frame, a sleeve journaled on said shaft, arms 100 rigidly connected with said sleeve and having a connection with said cutter supporting frame, and means for rotating said sleeve on said shaft to cause said arms to raise and lower said cutter supporting frame relative 105 to said main frame.

18. In a mining machine, a main frame, a supplemental frame pivotally connected with said main frame and arranged to swing vertically relative to said main frame, a kerf-cutter mounted on said supplemental frame, 110 a plate arranged to rest upon said main frame and constituting a support upon which said supplemental frame is arranged to slide horizontally, arms pivotally connected with said plate and with said main frame, and worm gearing for swinging said arms about their pivotal connection with said main frame to raise and lower said plate to adjust said supplemental frame and said kerf cutter vertically relative to said main frame and lock said supplemental frame at adjusted elevation. 115

19. In a mining machine, a main frame, a supplemental frame carried by said main 125 frame and movable vertically relative thereto kerf-cutting mechanism carried by said supplemental frame, lever mechanism for raising and lowering said supplemental frame and said kerf-cutting mechanism relative to said 130

main frame, worm gearing for operating said lever mechanism, and friction driving mechanism for said worm gearing to protect the same if said cutting mechanism meets an obstruction.

20. In a mining machine, a main frame, a cutter supporting frame mounted on said main frame and vertically adjustable relative thereto, kerf cutting mechanism carried by said cutter-supporting frame lever mechanism for raising and lowering said cutter supporting frame together with said cutting mechanism relative to said main frame, worm gearing for operating said lever mechanism, a shaft for driving said worm gearing having a friction cone thereon to protect said cutting mechanism, a drive shaft having a pair of friction cones slidably mounted thereon and movable into and out of engagement with said first mentioned friction cone for operating said shaft in either direction, a motor carried by said main frame for driving said power shaft, and means for operating said cutting mechanism.

25. 21. In a mining machine, the combination with a main frame, of a supplemental frame mounted on said main frame for lateral adjustment relatively thereto, an upright sleeve connected to said supplemental frame and overhanging one end of said main frame, a horizontally arranged kerf-cutter, an upright trunnion at the rear end of said kerf-cutter and journaled in said upright sleeve to pivotally support said kerf-cutter at the floor of the mine chamber, means for holding said kerf-cutter in fixed position relative to said sleeve, and means for moving said supplemental frame laterally together with said kerf-cutter.

30. 22. In a mining machine, a main frame, a supplemental frame adjustably mounted on said main frame, a bearing sleeve carried by said supplemental frame and having an upright axis, a second bearing sleeve rotatably mounted in said first mentioned sleeve, a cutter bar rigidly carried by said second sleeve and extending horizontally therefrom, a chain cutter mounted on said cutter bar, a shaft journaled in said second mentioned sleeve and having a sprocket thereon for driving said chain cutter, a motor carried by said main frame, and means for connecting said shaft with said motor to be driven thereby.

35. 23. In a mining machine, the combination with a main frame, of a supplemental frame mounted on said main frame and adjustable laterally relatively thereto on an upright axis at the rear ends of said frames, a horizontally arranged cutting element, means connecting one end of said cutting element with said supplemental frame to hold such cutting element in horizontal position while permitting lateral swinging movement thereof relatively to said supplemental frame, means for holding said cutting element in fixed adjusted relation

to said supplemental frame, and means for operating said cutting element in any of its adjusted positions on said supplemental frame.

24. In a mining machine, the combination with a main frame, of a supplemental frame pivotally connected to the rear portion of said main frame for lateral movement relatively thereto on an upright axis, a cutting element, a pivotal support at the forward end of said supplemental frame for the rear end of said cutting element, and power mechanism for swinging said cutting element about its pivotal support on an upright axis and for locking said cutting element in its various adjusted positions relatively to said supplemental frame.

25. In a mining machine, the combination with a main frame, of self-contained self-propelling mechanism therefor, a supplemental frame movable rectilinearly relatively to said main frame, a cutting element, and means for pivotally supporting said cutting element on an upright axis on said supplemental frame with the space in front of said supplemental frame free and unobstructed except for said upright pivotal support and said cutting element, means for adjusting the position of said upright pivotal support, a motor for swinging said cutting element about its upright pivotal support relatively to said supplemental frame, and worm gearing connecting said motor with said cutting element to hold the latter in its various adjusted positions.

26. In a mining machine, the combination with a main frame, of a supplemental frame pivoted to the rear end of said main frame to swing laterally upon said main frame on an upright axis, a cutter bar pivotally mounted on the forward end of said supplemental frame for lateral movement relatively thereto on an upright axis, self-acting power mechanism for swinging said cutter bar about its upright axis on the forward end of said supplemental frame, additional self-acting power mechanism for swinging said supplemental frame together with said cutter bar on the upright axis at the rear end of said main frame, and means for holding said frame against movement about their respective axes independently of one another.

27. A track-mounted mining machine comprising a supporting frame, cutting mechanism carried on said frame, a drive shaft for said cutting mechanism and extending longitudinally of said supporting frame, propelling mechanism, said propelling mechanism comprising a cross shaft, and differential change speed gearing between said drive shaft and said cross shaft to effect the feeding of the cutting mechanism.

28. In a mining machine, a main frame, wheels for supporting said frame on a mine track a supplemental frame mounted on said

main frame, a cutter carried by said supplemental frame, a drive shaft extending longitudinally of said main frame, a driven shaft extending longitudinally of said supplemental frame, operating mechanism for propelling said main frame along said track and arranged to be driven by the drive shaft extending longitudinally of said frame, and cutter mechanism arranged to be driven by the driven shaft carried by said supplemental frame.

29. A mining machine comprising cutting mechanism, a frame having a main drive shaft journalled therein, a main cross shaft journalled in said frame, a pair of supplemental cross shafts, journalled in said frame and arranged to be alternately driven in opposite directions by said main drive shaft, gearing for selectively connecting said main cross shaft with said supplemental cross shafts for driving said main cross shaft in either direction, and operating mechanism for said cutting mechanism comprising means driven by said main cross shaft to effect the feed of said cutting mechanism.

30. A mining machine comprising a frame, a main drive shaft extending longitudinally thereof, a main cross shaft extending transversely of said main drive shaft, supplemental cross shafts on opposite sides of said main cross shafts and arranged to be driven by said main drive shaft in opposite directions, gearing for selectively connecting said main cross shaft with said supplemental cross shafts to drive said main cross shaft in either direction, said gearing including differential mechanism for imparting a slow and powerful movement to said main cross shaft, and propelling mechanism for the mining machine arranged to be driven by said main cross shaft.

31. The combination with a mining machine, of a driven shaft therefor, a gear loosely mounted on said driven shaft, pinions meshing with said gear for rotating said gear in either direction, planetary gearing driven by said first mentioned gear and arranged to impart a differential movement to said driven shaft, and mechanism connected to said driven shaft for feeding said mining machine.

32. The combination with a mining machine, of a driven shaft therefor, two sets of planetary gearing pivoted on parallel circumferences and connected to said driven shaft, means for operating said planetary gearing to drive said shaft in either direction, and propelling mechanism connected to said driven shaft to be driven thereby to move the entire mining machine to effect feeding thereof.

33. The combination with a mining machine, of a drive shaft therefore, a pair of supplemental shafts arranged adjacent said drive shaft and parallel therewith, a disc

loosely mounted on said drive shaft and having gear teeth on the periphery thereof, pinions carried by said supplemental shafts and meshing with said disc for driving said disc in opposite directions, a fixed member having bearings through which said shafts pass, gear teeth formed on said fixed member, short shafts journalled in said disc and having pinions on the opposite ends thereof, the pinions on one end of said shafts being arranged to mesh with the gear teeth in said fixed member, a rotary member mounted on said shaft and having gear teeth arranged to mesh with the pinions on the other ends of said short shafts, means for connecting said drive shaft with said rotary member to be driven thereby, and feeding mechanism for said mining machine arranged to be driven by said drive shaft.

34. In a mining machine, a main frame, cutting mechanism mounted thereon, a track for supporting said frame, means comprising a drum for shifting said frame and track relative to one another to adjust the position of said cutting mechanism, a motor for operating said drum, and differential reversible change speed gearing for connecting said motor with said drum.

35. A mining machine comprising a frame, a track for supporting said frame, a main drive shaft extending longitudinally of said frame, a cross shaft carried by said frame, means comprising a drum carried by said cross shaft for shifting said frame and track relative to one another to adjust the position of said mining mechanism, and differential reversible gearing for connecting said cross shaft with said main drive shaft.

36. In a mining machine, a truck arranged to travel on a mine track, a supplemental track carried by said truck and shiftable longitudinally thereof, means for moving said supplemental track into and out of contact with the surface of a mine floor, and power mechanism for shifting said truck and supplemental track longitudinally relative to one another.

37. A mining machine comprising a truck arranged to travel on a mine track, a supplemental track for said machine, shoes carried by said truck and adjustable vertically relative thereto, said supplemental track being slidably carried by said shoes, a drum mounted on said truck, means for rotating said drum in either direction, a pair of cables wound in opposite directions about said drum and having their ends connected with the opposite ends of said supplemental track, a motor for driving said drum to adjust the position of the mining machine, and gearing for connecting said motor with said drum.

38. In a mining machine, a frame, a slideway supported beneath said frame and adjustable vertically relative thereto, a track carried by said slideway, means for shifting

said track and slideway longitudinally relative to one another, and power mechanism for operating said adjusting means to lift and support said frame from said track.

- 5 39. In a mining machine, a frame, longitudinally spaced arms pivotally carried by said frame, track engaging shoes carried by said arms, a track slidably mounted in said shoes, worm gearing for shifting said arms 10 to raise and lower said shoes and the track carried thereby relative to said frame, and to lift said frame relative to said track when said track rests upon the surface of the mine floor, and a motor for driving said gearing.
- 15 40. In a mining machine, a truck arranged to travel upon a mine track, a supplemental track carried by said truck and arranged to be extended in front of said truck, and jacks for adjustably supporting the front end of 20 said supplemental track.

- 25 41. In a mining machine, a truck having cutting mechanism carried thereon and arranged to travel on a mine track, a supplemental track carried by said truck and arranged to be extended in front of said truck, means for shifting the weight of said truck to said supplemental track, and a pair of independently adjustable jacks for supporting the opposite sides of the front end of said 30 supplemental track.

- 35 42. In a mining machine, a truck, a motor carried by said truck, mechanism driven by said motor to propel said truck along a mine track, a supplemental track carried by said truck, means for shifting the weight of said truck from said mine track to said supplemental track, and means for feeding said truck along said supplemental track during 40 a mining operation.

- 45 43. In a mining machine, a truck having wheels arranged to travel upon a mine track, cutting mechanism carried by said truck, a motor mounted on said truck, a drive shaft operated by said motor, gearing connecting said drive shaft with said wheels to cause said truck to travel along a mine track, means for throwing said gearing into and out of driving connection with said motor shaft, and a supplemental track adapted to project beyond 50 said first-named track for supporting said truck during a mining operation.

- 55 44. In a mining machine, a truck having wheels arranged to travel upon a mine track, a motor carried by said truck, means operated by said motor for propelling said truck along a mine track, a supplemental track carried by said truck and movable into and out of contact with the floor of a mine chamber, means for shifting the weight of said truck to 60 said supplemental track, drums mounted on said truck, cables arranged to be wound on said drums and having their ends arranged to be connected with anchoring mechanism, and means for rotating said drums to

move said truck forwardly upon said supplemental track during a mining operation. 65

45. In a mining machine, a drive shaft, reversible change speed mechanism for operating said drive shaft, a plurality of drums mounted on said drive shaft and arranged to be rotated thereby and adapted to propel the entire machine, a supplemental track for supporting said mining machine during a mining operation, a movable cutter frame, and cables on said drums for operating said track and said cutter frame. 70 75

46. A mining machine comprising a drive shaft, one-way chain cutter driven by said drive shaft, a cross shaft, propelling mechanism adapted to be driven by said cross shaft to effect feeding of said one-way chain cutter, and reversible gearing for connecting said cross shaft with said drive shaft to retract the mining machine while said chain cutter retains its original driving direction. 80 85

47. In a mining machine, the combination with a main frame, of wheels for supporting said frame on a mine track, a cutter-supporting frame pivotally mounted at the rear portion of said main frame for lateral movement 90 along the front portion of said main frame, an elongated cutting element pivotally mounted on the forward end of said cutter-supporting frame for lateral swinging movement relatively to said supporting frame and 95 relatively to said main frame, means for holding said cutting element in adjusted position relatively to said cutter-supporting frame, and means for operating said cutting element including lateral movement of said cutter-supporting frame to secure lateral feed of said cutting element on a long arc 100 with the upright pivot between the cutter-supporting frame and said main frame as a center. 105

48. In a mining machine, a frame, a cutter carried by said frame and arranged to operate adjacent the floor of a mine chamber, a track carried by said frame and movable into and out of contact with the floor of the mine, and means for supporting said frame on said track and for adjusting said frame vertically relative to said track to regulate the height of said cutter above said mine floor. 110 115

49. In a mining machine, the combination with a wheeled track guided truck providing a base, a pivotal mounting thereon for a cutter bar, said mounting being pivotable about a vertical axis, a cutter bar pivoted on said mounting to swing about a vertical axis offset from said first-mentioned vertical axis, means whereby said bar may be disposed in a transverse plane beneath the top of a track with its pivot at one side of said track, means including a pair of alining apertures and a pin for holding said bar with its longitudinal axis in the same vertical plane that in- 120 125

cludes said vertical axes, and a plurality of apertures in one of said elements arranged at equal angles at opposite sides of the first-mentioned apertures in that element.

5. 50. In a mining machine, the combination with a wheeled track guided truck providing a base, a pivotal mounting thereon for a cutter bar, said mounting being pivotable about a vertical axis, a cutter bar pivoted on said mounting to swing about a vertical axis offset from said first-mentioned vertical axis, means whereby said bar may be disposed in a transverse plane beneath the top of a track with its pivot at one side of said track, means 10 including a pair of alining apertures and a pin for holding said bar with its longitudinal axis in the same vertical plane with said vertical axes, and an aperture at each side of one of the first-mentioned apertures in one of 15 said elements, said last-mentioned apertures being arranged at equal distances from said first-mentioned aperture at the opposite side of which they are arranged and being so disposed that said bar may make an acute angle 20 with the plane including said vertical axes.

51. In a mining machine, the combination of a wheeled track guided truck providing a base, a pivotal mounting thereon for a cutter bar, said mounting being pivotable about a 25 vertical axis, a cutter bar pivoted on said mounting to swing about a vertical axis offset from said first-mentioned vertical axis, means whereby said bar may be disposed in a transverse plane beneath the top of a track with its pivot at one side of said track, and means for holding said bar with its longitudinal axis in different positions relative to a plane including said axes including a plurality of apertures in one of said elements situated 30 when said bar occupies a predetermined relation to a horizontal line passing through said axes at opposite sides of the longitudinal axis of said bar and nearer the end of the cutter bar than said second-mentioned axis, and a cooperating sliding pin carried by another element.

52. In apparatus of the class described, the combination of a main track, a mining machine arranged to run on said main track by means of a plurality of supporting wheels and means adapted to enable the mining machine to be supported beyond the end of said supporting track during the operation of said mining machine while maintaining said supporting wheels in alinement with said main track, said means comprising a supplemental track in slidable relation with said mining machine.

53. In a mining machine, the combination with a main frame, of a cutter supporting frame carried by said main frame, a cutter pivotally connected to said supporting frame, means for tilting said cutter supporting frame and said cutter on a horizontal axis to hold the cutter up to clear a track during

transportation, means for holding said cutter supporting frame and said cutter rigidly fixed to said main frame, means for driving said cutter, means for advancing said main frame to effect feeding of said cutter, means for swinging said cutter supporting frame with said cutter held in fixed relation thereto to effect lateral feeding movement of said cutter relatively to said main frame, and means for swinging said cutter relatively to 70 said cutter supporting frame to effect feeding movement of said cutter relatively to both the main frame and said cutter supporting frame.

54. In a mining machine, the combination with a main frame, of self-contained self-propelling mechanism therefor, a cutter-supporting frame pivotally mounted on said main frame to swing laterally on an upright axis and vertically on a horizontal axis relatively to said main frame, cutting mechanism carried by said cutter-supporting frame, a motor on said main frame, driving mechanism between said motor and said cutting mechanism and comprising a shaft on said 85 cutter-supporting frame and movable therewith and comprising also a shaft on said main frame, and a clutch for operatively connecting said shafts when said cutter-supporting frame is in a predetermined position for 90 operation of said cutting-mechanism.

55. In a mining machine, a truck adapted to run upon a track, cutting mechanism thereon having a pivoted cutter bar provided with cutting elements moving in an orbit 100 within which the pivot of said bar is disposed, means whereby said bar may be disposed in a transverse plane beneath the top of said track with its pivot at one side of said track, and means whereby said bar pivot may 105 be swung in said plane either bodily with said bar or while the latter is released for free movement relative to its pivot.

56. In a mining machine, the combination with a truck adapted to travel on a mine 110 track, of a supplemental track adapted to be carried by said truck, means for moving said supplemental track into and out of position to support said truck, and power mechanism for propelling said truck along said supplemental track when supported by the latter.

57. In a mining machine, the combination with a frame, of a portable truck, a track portable therewith, connections between said frame and said portable track for supporting the latter at adjusted elevations, means for operating said connections to adjust the elevation of said portable track, and means for moving the truck along said track after the latter is lowered and occupies a stationary 120 position.

58. In a mining machine, the combination with a frame, of a plurality of arms pivoted to said frame, a track carried by said arms for slidably supporting said frame, and

means for shifting said arms to lift and lower said track carried thereby and also to lift the frame for support by said track.

59. In a mining machine, the combination with a frame, of a track carried by said frame to slidably support the latter, means for shifting the track relatively to said frame, and means for moving said frame relatively to said track when said frame is supported on 10 said track.

60. In a mining machine, the combination with a frame, of a plurality of arms pivoted to said frame, a track carried by said arms, means for moving said arms to lay the track 15 and support said frame on the track, and means for moving said frame along said track while supported thereon.

61. In a mining machine, the combination with a truck adapted to travel on a mine 20 track, of a supplemental track carried by said truck, means for laying said supplemental track to extend beyond the end of said mine track, and means for supporting the front end of said supplemental track.

62. In a mining machine, the combination with a truck adapted to travel on a mine track, of a supplemental track carried by said truck, means for laying said supplemental track to extend in advance of said 30 mine track, and means for supporting the front end of said supplemental track at various elevations.

63. A mining machine comprising a truck having cutting mechanism carried thereon, 35 said truck being adapted to travel on a mine track, a supplemental track carried by said truck, means for laying the supplemental track to extend beyond said mine track, means for supporting the opposite sides of 40 the front end of said supplemental track, and mechanism for shifting the mining machine for support from said mine track to said supplemental track.

64. A mining machine comprising a truck 45 adapted to travel on a mine track, a supplemental track adapted to be laid to extend from said mine track and beyond the latter, means for lifting the mining machine bodily upward off the mine track while being supported by said supplemental track, and means for propelling the mining machine along said supplemental track when supported thereon.

65. A mining machine comprising a truck adapted to travel on a mine track, a supplemental track adapted to extend beyond said mine track, means for shifting the weight of 55 said mining machine to said supplemental track without moving said mining machine along the mine track, and means for propelling the mining machine along said supplemental track to extend in advance of said mine track.

66. A mining machine comprising a truck 60 adapted to travel on a mine track, a supplemental track adapted to extend in advance

of said main track, and means applied to said mining machine while on said mine track for shifting the weight thereof onto said supplemental track for support by the latter.

67. A mining machine comprising a truck 70 adapted to travel on a mine track, a supplemental track having rails spaced laterally from the rails of said mine track, and means for supporting said mining machine on said supplemental track to extend in advance of 75 said mine track.

68. A mining machine comprising a truck adapted to travel along a mine track, a supplemental track incapable of receiving said truck but adapted to extend from said mine 80 track in advance thereof, means for supporting the mining machine on said supplemental track, and means comprising rope-winding mechanism for propelling said mining machine along said supplemental track to extend beyond said mine track. 85

69. A mining machine comprising a truck adapted to travel along a mine track, a supplemental track incapable of receiving said truck but extending in advance of said mine 90 track, means for shifting weight of said mining machine from said mine tracks to said supplemental track, and means comprising rope-winding mechanism on said truck for propelling the mining machine along said 95 supplemental track and partly off the end of said mine track.

70. A mining machine comprising a frame, a cutter carried by said frame, a track carried by said frame, and means for supporting said 100 mining machine on said track at various elevations.

71. A mining machine comprising a truck adapted to travel on a mine track, cutting mechanism mounted on said truck, a supplemental track carried by said truck, and means for supporting the mining machine on said supplemental track at adjusted elevation to secure adjustment in elevation of said cutter. 105

72. A mining machine comprising a truck adapted to travel along a mine track, a supplemental track incapable of receiving the wheels of said truck, and means for supporting the mining machine partly on one of said trucks and partly on the other while extended beyond the forward end of said mine track. 110 115

73. A mining machine comprising a truck having wheels adapted to run on a mine track, a supplemental track having rails spaced laterally from the rails of the mine track but in parallelism therewith and extending from said mine track beyond the end thereof, and means for supporting the forward portion of said truck on said supplemental track with 120 the forward wheels of said truck out of contact with either track but in alinement with the rails of the mine track. 125

74. In coal-mining apparatus adapted to 130 cut a kerf the bottom of which is approximate-

ly even with the mine floor in a narrow entry while supported and guided by the mine track during its cutting operation, the combination with a main frame, of track wheels for supporting said frame on a mine track, an overhanging arm mounted on said main frame in position for its outer end to swing across the mine track, an elongated cutter bar pivotally mounted on the outer end of said overhanging arm in position to swing horizontally, the range of the lateral movement of the overhanging arm and the range of lateral movement of the cutter bar on the outer end of said overhanging arm being such as to permit the cutter bar to be at one side of the mine track during its feeding-in movement and on the other side of the track with its bottom line below the top of the track during its feeding-out movement, means for effecting reciprocation of the machine bodily on the mine track to effect feeding of the cutter bar during a portion of its operation, means for swinging said overhanging arm laterally to effect feeding of the cutter bar during another portion of its operation, and means for locking the cutter bar at its pivot on the outer end of the overhanging arm in a plurality of positions.

75. In a mining machine, the combination with a truck adapted to travel on a mine track, of an elongated chain cutter, of means for suspending said chain cutter by connection to the rear end thereof for operation at approximately the level of the mine floor on which the track is laid and on the sides of said track at such level as well as in advance of the end of the track, mechanism for moving said suspended means relatively to the truck to feed the cutting mechanism on a long radius extending longitudinally of the truck to the rear portion thereof, and means for driving said cutting mechanism at such level and in such positions relative to the truck.

76. In a mining machine, the combination with a track-mounted supporting frame, of self-contained self-propelling mechanism therefor, an elongated swinging kerf cutter, means pivotally connected to the rear end of said kerf cutter for supporting the same on said frame in position to cut a kerf in a plane substantially in line with the mine floor, means for adjusting the position of said kerf cutter at such pivotal connection for kerf cutting beyond the ends of said track and at the sides thereof in such plane, and means for operating said kerf cutter in such adjusted positions including the feed thereof.

77. In coal mining apparatus comprising undercutting mechanism supported on and guided by a mine track extending approximately at right angles to the face of the coal to be undercut while performing its cutting operation, the combination with a main frame mounted on track wheels adapted to run on the mine track, of an overhanging arm pivotally mounted on said main frame to swing

horizontally with its outer end moving from one side of the track to the other in a path forwardly of said main frame toward the coal face, an elongated cutter bar pivotally mounted on the outer end of the overhanging arm to swing horizontally adjacent the plane of the floor on which the mine track is laid, means for effecting reciprocation of the machine bodily on the mine track to effect feeding of the cutter-bar during a portion of its operation, means for locking the cutter bar on the outer end of the over-hanging arm in a plurality of positions during the reciprocation of the machine to effect the cutting of kerfs in the plane of the floor at the sides of the forward end of the track, and means for swinging said arm together with said cutter bar laterally to cut an additional kerf in the plane of the floor to connect the said side kerfs.

78. In a mining machine, the combination with a track-mounted main frame, of self-contained self-propelling mechanism therefor, a supplemental frame mounted on said main frame for lateral movement relatively thereto, an elongated kerf-cutter mounted on said supplemental frame in position to cut a kerf the bottom of which is approximately in the plane of the mine floor, an adjustable joint between said kerf-cutter and said supplemental frame to permit the rear portion of said kerf-cutter to be located in a narrow space between the track and the adjacent mine wall for the cutting of a kerf at such level, and means for operating said kerf-cutter including rectilinear movement thereinto of the working face, and lateral movement transversely of the working face.

79. In a mining machine, the combination with a track-mounted main frame, of a supplemental frame pivoted at its rear portion to said main frame for lateral swinging movement across the front end of said main frame, an elongated kerf-cutter, a depending neck for supporting said kerf-cutter from said supplemental frame in position to cut a kerf the bottom of which is approximately in the plane of the mine floor on which the track is laid, means for holding the kerf-cutter in fixed relation to said supplemental frame, at an adjusted angle between said kerf-cutter and said supplemental frame, to permit said kerf-cutter to extend between the mine track and mine walls at the sides of the track and extend in directions along the mine walls approximately parallel to the track, means for effecting the reciprocation of the mining machine to secure rectilinear feed of said cutter into the work face in advance of the end of the track and out from said face at the opposite walls, and means for swinging the cutter on the pivot of said supplemental frame to secure a feed across the working face on a long radius.

80. In a mining machine, the combination with a main frame, of a supplemental frame

mounted thereon for lateral movement relatively thereto, an elongated kerf cutter pivotally connected to said supplemental frame for swinging movement relatively thereto on 5 an upright axis, means for holding said elongated kerf-cutter in adjusted angular relation to said supplemental frame in accordance with the position of the latter on one side or the other of said main frame, means 10 for effecting the reciprocation of said main frame to secure rectilinear feed of said kerf-cutter, means for moving said supplemental frame laterally to secure transverse feed of said kerf-cutter, and means for driving said 15 kerf-cutter.

81. In a mining machine, the combination with a track-mounted main frame, of an elongated supplemental frame pivoted at its rear end to the rear portion of said main frame, 20 an elongated kerf cutter pivotally connected to the forward end of said supplemental frame, means for holding the kerf-cutter in adjusted angular relation to said supplemental frame, means for effecting the reciprocation 25 of said main frame to secure rectilinear feed of said kerf-cutter, means for swinging said supplemental frame together with said kerf-cutter to secure arcuate feed of the latter on a long radius, and means for driving 30 said kerf-cutter during the feeding thereof.

82. In a mining machine, the combination with a track-mounted main frame, of a supplemental frame pivotally connected to the rear portion of said main frame for swinging 35 movement on an upright axis across the front end of said main frame, an elongated kerf-cutter, means for suspending said elongated kerf-cutter from said supplemental frame in position to cut a kerf the bottom of which 40 is approximately in the plane of the mine floor, means for holding the kerf-cutter in adjusted angular relation to said supplemental frame to permit said kerf cutter to extend approximately parallel to the mine wall in 45 the spaces between the track and the adjacent mine walls, means for advancing the kerf cutter rectilinearly from the space between the track and one of the mine walls into the base of the working face, and re- 50 tracting said kerf cutter from the working face into the space at the opposite side of the mine track adjacent the opposite mine wall, means for swinging the supplemental frame laterally to secure feed of said kerf cutter 55 across the working face, and means for driving said kerf cutter during the rectilinear feed thereof into the working face and during the rectilinear feed thereof back from the face in a narrow entry.

83. An entry cutting apparatus comprising, in combination, a supporting frame, a kerf cutting element, a supplemental elongated frame extending along the upper portion of said first-named frame and downwardly at the front thereof to hold said kerf

cutting element in position to cut a kerf at the level of the floor of the mine chamber, 70 positioning, guiding and shifting means for said supplemental frame and kerf cutting element, for guiding and shifting the latter to cut substantially straight rib cuts in opposite directions at the floor level, one on each side of the machine and in advance thereof, and for positioning and shifting said kerf cutting element to cut a kerf between the end 75 of the advance straight rib cut and the guiding of the retractile straight rib cut at the floor level to provide a kerf having parallel lines extending the entry along the floor level, the width of the entry being less than twice 80 the distance from the axis of swinging shifting movement to the end of the cutter element relatively to the entry during the straight rib cuts, and supplemental guiding means for supporting the kerf cutting element to permit the cutting of an increment 85 of a previous kerf to extend the entry.

84. An entry cutting installation comprising, in combination, a kerf cutting element and positioning, guiding and shifting means 90 therefor for positioning, guiding and shifting said kerf cutting element to cut substantially straight rib cuts in opposite directions at the floor level, one on each side of the machine and in advance thereof, and for positioning and 95 shifting said kerf cutting element to cut a kerf between the end of the advance straight rib cut and the beginning of the retractile straight rib cut to provide a kerf having parallel sides extending the entry, the width of the entry being less than twice the distance from 100 the axis of swinging shifting movement to the end of the cutter bar and determined by the angularity of the cutter bar relative to the entry during the straight rib cuts, said guiding means being extensible toward the limit 105 of the prior kerf to permit the cutting of a plurality of such kerfs as increments extending an entry.

85. In an entry cutting installation, the combination with a truck adapted to travel on a mine track, of a kerf cutting element mounted on said truck to swing laterally beyond the forward end thereof, means for moving said truck together with said kerf cutting element along said track to effect the cutting of substantially straight rib cuts in opposite directions at the floor level, one on each side of the machine and in advance thereof, means for swinging said kerf cutting element to cut a kerf between the end of the advance straight rib cut and the beginning of the retractile straight rib cut to provide a kerf having parallel sides extending the entry, 110 the width of the entry being less than twice the distance from the axis of swinging movement to the end of the kerf cutting element and determined by the angularity of the latter 115 relative to the entry during the straight rib cuts, and means for supporting the truck in 120 125 130

extended positions toward the limit of the prior kerf to permit the cutting of a plurality of such kerfs as increments extending an entry.

- 5 86. In a mining machine, the combination with a truck adapted to travel on a mine track positioned approximately perpendicular to an upright mine wall, of cutting means adapted to cut in such mine wall in front of said track, 70
10 a kerf extending transversely thereof, supporting means carrying the cutting means and mounted on the truck for arcuate movement about an upright axis, whereby the cutting means can be carried, while cutting, across 75
15 the vertical longitudinal planes of the truck from a position on horizontal lines at either of several angles to the said planes, on one side of the track, to a position on horizontal lines at either of several angles, on the other side of the track, manually operable means 80
20 for locking said supporting means relative to the truck in any of said several angular positions, and means for extending the support of said truck beyond the forward end of said 85
25 mine track.

- 30 87. In a mining machine, the combination with a wheeled truck adapted to travel freely forward and backward on a mine track located approximately perpendicular to a wall in a mine, of cutting mechanism adapted to 90
35 cut a kerf extending transversely of the track and in front thereof in the mine wall, supporting means for said cutting means and mounted on and extending over said truck and movable arcuately about an upright axis 95
40 whereby the cutting means can be carried across the vertical longitudinal planes of the track from a position on horizontal lines at an acute angle to said planes on one side of the track to a position at a similar acute angle to the said planes on the other side of the track, means for holding said supporting 100
45 means rigid relative to the truck in either of said angular positions, and extensible track mechanism for supporting the machine in advance positions relative to said mine track.

- 50 88. In a mining machine, the combination with a main frame, of wheels for supporting said main frame on a mine track, an elongated cutter-supporting frame pivotally mounted at the rear portion of said main frame for lateral arcuate movement on an upright axis, an elongated chain kerf cutter connected to the outer end of said cutter-supporting frame 105
55 and extending out beyond the latter and means for operating said chain kerf cutter including lateral feeding movement thereof on a long radius extending from said upright axis along said elongated frame to the outer 110
60 end of said kerf cutter.

- 65 89. In a mining machine, the combination with a main frame, of wheels for supporting said frame on a mine track, a cutter-supporting frame having a horizontal elongated portion pivotally connected to the rear portion

of said main frame for lateral swinging movement on an upright axis and having an upright portion depending from the forward end of said horizontal portion for movement arcuately with the latter across the front 70
75 end of said main frame, an elongated chain kerf-cutter connected at its rear end to the lower end of said upright portion for movement with the latter while occupying an undercutting position in front of the mine track, 80
85 means for driving said chain kerf cutter, and means for swinging said cutter supporting-frame together with said chain kerf-cutter on said upright axis to secure arcuate feeding movement of said kerf cutter with the outer end of the latter traveling along an arc on a radius equal approximately to the combined lengths of said cutter supporting frame and said chain kerf cutter.

90 90. In a mining machine, the combination with a main frame, of a supplemental frame mounted thereon for lateral movement relatively thereto, a kerf-cutter mounted on said supplemental frame, means for operating said kerf cutter, means for adjusting the elevation of said supplemental frame together with said kerf cutter, and mechanism comprising a laterally extending groove on said supplemental frame for receiving an extension from said adjusting means to lock the supplemental 95
95 frame and said kerf cutter against up or down movement while permitting lateral movements thereof.

95 91. In a mining machine, the combination with a main frame, of a supplemental frame 100
105 pivotally connected to said main frame for swinging movements up and down and also laterally relatively to said main frame, a chain kerf cutter mounted on said supplemental frame to move bodily therewith up and down and also laterally, lifting and lowering mechanism between said main frame and said supplemental frame, and abutment locking mechanism comprising an arcuate groove in said supplemental frame 110
110 for receiving an extension from said lifting and lowering mechanism to limit the downward movement of said kerf cutter and lock the same against upward movement during operation while permitting lateral swinging movement of said supplemental frame and said kerf cutter.

115 92. In a mining machine, the combination with a main frame, of a supplemental frame 120
125 pivotally mounted on said main frame for lateral and up and down swinging movements, lifting and lowering mechanism comprising locking worm gearing, an actuating arm and a slide plate pivotally connected to said arm and engaging a lower flat surface of the forward portion of said supplemental frame, plane kerf cutting mechanism mounted on the said supplemental frame, means for operating said kerf cutting mechanism, and locking mechanism comprising an arcuate 120
125

groove in the forward portion of said supplemental frame to receive an arcuate extension from said slide plate to form an abutment limiting the downward movement 5 of the supplemental frame and said kerf-cutter where the latter occupies an approximately horizontal position and to form an interlock to prevent upward movement of said kerf-cutter during operation while permitting lateral swinging movement of said supplemental frame and said kerf cutter.

93. In a mining machine, the combination with a truck adapted to travel on a mine track, of a supplemental track of a different 15 gauge from that of the mine track, means for supporting the truck on said supplemental track to permit the latter to extend beyond the forward end of said mine track, and power mechanism for propelling the truck along 20 said supplemental track when supported by the latter and while extended beyond the forward end of said track.

94. A mining machine comprising a truck adapted to travel on a mine track, of a supplemental track having a gauge differing 25 from that of the mine track but adapted to rest on the ties of the mine track and extend beyond the forward end of the latter, and means for supporting said truck on said supplemental track to permit such truck to be 30 extended beyond the forward end of said mine track.

95. A mining machine comprising a truck 35 adapted to travel on a mine track, of a supplemental track having a gauge narrower than that of the mine track and adapted to be located between the rails of the latter, means for supporting the truck on the supplemental track to permit the truck to extend 40 beyond said mine track, and means for propelling the truck along said supplemental track.

96. A mining machine comprising a truck 45 adapted to travel on a mine track with its forward end near an upright mine wall, of a supplemental track having a narrower gauge than that of the mine track and adapted to rest on the ties of the latter between the rails thereof and movable beyond the forward end 50 of said mine track, means for supporting the mining machine on said supplemental track with the truck thereof extended beyond the forward end of said mine track to permit operation of the mining machine in various extended positions of the mining machine beyond the forward end of said mine track.

97. A mining machine comprising a truck 60 adapted to travel on a mine track, a supplemental track adapted to extend in advance of said mine track, means between said supplemental track and said truck for supporting part of the weight of the latter, and means for propelling the mining machine along said supplemental track to extend the mining ma-

chine beyond the forward end of said mine 65 track.

98. A mining machine comprising a supporting frame movable along a track, a supplemental track adapted to extend in advance of the first-named track, means between said supplemental track and the mining machine for supporting part of the weight of the latter, and means for propelling the mining machine along said supplemental track when the latter is extended beyond the forward end of 75 said first-named track to advance the mining machine to various operating positions in front of said first-named track while the mining machine has its forward portion supported by said supplemental track and its rear 80 portion supported partly by said first-named track and partly by said supplemental track.

99. In a mining machine, a truck adapted to run upon a track, cutting mechanism thereon having a pivoted cutter bar provided with cutting elements moving in an orbit within which the pivot of said bar is disposed, means whereby said bar may be disposed in a transverse plane below the top of said track with its pivot at one side of said track, and means 90 for operating said bar to insert a cut in said plane across the end of the track including motor driven means for swinging the bar pivot and a releasable connection operative to hold the bar in fixed relation to its pivot or 95 when released automatically to cause relative movement therebetween upon a continued swinging movement of the pivot.

100. In a mining machine, a truck adapted to run upon a track, cutting mechanism thereon having a pivoted cutter bar provided with cutting elements moving in an orbit within which the pivot of said bar is disposed, means whereby said bar may be disposed in a transverse plane below the top of said track with its pivot at one side of said track, and means 100 for operating said bar to insert a cut in said plane across the end of the track including a releasable connection between the bar and its pivot and motor driven means whereby said 105 pivot and bar may be swung thereby bodily or said pivot may be swung thereby while the tip of the bar remains substantially stationary.

101. In a mining machine, a truck adapted 115 to run upon a track, cutting mechanism thereon having a pivoted cutter bar provided with cutting elements moving in an orbit within which the pivot of said bar is disposed, means whereby said bar may be disposed in a transverse plane beneath the top of said track with its pivot at one side of said track, and means whereby said bar may insert a cut in said plane across the end of the track including a series of holes and a cooperating pin for holding 120 said bar in different angular positions relative to said pivot in said plane.

102. In mining apparatus, the combination

with supporting framework, of wheels connected to said framework and adapted to travel on a mine track, of kerf cutting mechanism mounted on said framework to occupy 5 a horizontal position, a supplemental track, parallel motion mechanism comprising parallel shoes having longitudinal grooves for receiving the heads of the rails of said supplemental track, means for operating said 10 parallel motion mechanism to lower said supplemental track onto the ties between the rails of said mine track and to elevate said framework to adjust the elevation of said kerf cutting mechanism to various positions 15 in parallel planes, and means for propelling the said framework and said kerf cutting mechanism while supported on said supplemental track and while said parallel shoes slide along the rails of said supplemental 20 track.

103. In a mining machine, the combination with a truck adapted to travel on a mine track, of cutting mechanism mounted on said truck and having a pivoted cutter-bar provided 25 with cutting elements moving in an orbit within which the pivot of said bar is disposed, means whereby said bar may be disposed in a transverse plane beneath the top of the mine track with its pivot at one side 30 of said track, means including a series of holes and a co-operating pin for holding said cutter-bar in different angular positions relative to its pivot in said plane, motor driven means for feeding said bar at will rectilinearly 35 early either forwardly or rearwardly during cutting in said plane, and motor driven means for swinging said bar pivot at will with the cutting mechanism moving in said plane across the end of said truck in front of said 40 track.

104. In a mining machine, a truck adapted to run upon a track, cutting mechanism thereon having a pivoted cutter bar provided with cutting elements moving in an orbit within 45 which the pivot of said bar is disposed, means whereby said bar may be disposed in a transverse plane below the top of said track with its pivot at one side of said track, and means for operating said bar to insert a cut in said 50 plane across the end of the track including motor driven means for swinging the bar pivot, and a releasable connection operative to hold the bar fixed in opposite acute angled 55 position and releasable to permit free movement relative to its pivot.

105. In a mining machine, a truck adapted to run upon a track, cutting mechanism thereon having a pivoted cutter bar provided with cutting elements moving in an orbit within 60 which the pivot of said bar is disposed, means whereby said bar may be disposed in a transverse plane beneath the top of said track with its pivot at one side of said track, motor driven means for at will driving the truck wheels 65 reversely to effect reverse rectilinear bar

movement during cutting in said plane, motor driven means for at will swinging said bar pivot while the bar is in said plane, and means whereby said bar may be adjusted into different fixed relations to said pivot. 70

106. In a mining machine, a truck adapted to run upon a track, cutting mechanism thereon having a pivoted cutter bar provided with cutting elements moving in an orbit within which the pivot of said bar is disposed, means whereby said bar may be disposed in a transverse plane beneath the top of said track with its pivot at one side of said track, means including a series of holes and a co-operating pin for holding said cutter bar in different angular positions relative to its pivot in said plane, motor driven truck wheel driving means for feeding said bar at will reversely rectilinearly during cutting in said plane, and motor driven means for swinging said bar pivot at will in said plane across the end of said truck in front of said track. 80

107. In a mining machine, the combination of a wheeled track guided truck providing a base arranged in fixed relation to the axes of the wheels, a vertically pivoted frame mounted above said base, supporting means for the latter permitting vertical adjustment thereof relative to said base, a cutter chain carrying cutter bar member carried by and pivotally 90 mounted with respect to said frame for swinging movement about an axis parallel to but offset from the axis of said frame, a motor on said frame operatively connected to said cutter chain, and means for holding said bar in different adjusted positions relative to said frame including a plurality of holes in one of said members, a hole in the other and a pin adapted to be inserted in said holes. 95

108. In a mining machine, the combination with a self-propelling wheel supported truck, of a turntable rotatably mounted upon said truck and vertically adjustable relative thereto, an overhanging bracket carried by said turntable, a horizontally projecting elongated kerf-cutter mounted upon said bracket and rotatable thereon in horizontal planes, means to lock said kerf-cutter in either of several positions of angular adjustment relative to said bracket, and means mounted upon said turntable to actuate the kerf-cutter and to rotate the turntable as and for the purpose set forth. 105

109. In a mining machine, the combination with a self-propelling wheel supported truck, of a turntable rotatably mounted upon said truck and vertically adjustable relative thereto, an overhanging downwardly projecting bracket carried by said turntable, a horizontally projecting elongated kerf-cutter mounted upon the lower end of said bracket and rotatable thereon in horizontal planes, means to lock said kerf-cutter in either of several positions of angular adjustment relative to said turntable, and means mounted upon said turntable to actuate the kerf-cutter and to ro- 110 115 120 125 130

tate the turntable as and for the purpose set forth.

110. In a mining machine, the combination with a self-propelling wheel supported truck, 5 of a turntable rotatably mounted upon said truck and vertically adjustable relative thereto, an overhanging downwardly projecting bracket carried by said turntable, a horizontally projecting elongated kerf-cutter mounted upon the lower end of said bracket and rotatable thereon in horizontal planes, means 10 to lock said kerf-cutter in either of several positions of angular adjustment, means mounted upon said turntable to actuate the 15 kerf-cutter and to rotate the turntable, and means to lock the turntable.

111. In a mining machine, the combination with a supporting frame, of a cutter-bar mounted on said frame in a relatively 20 low plane and having an upwardly offset portion at the rear end thereof, a chain cutter on said cutter-bar, an upright driving shaft, a sprocket wheel on said shaft to drive said cutter chain, a gear on said shaft, means 25 on said frame for rotating said gear to drive said sprocket wheel, a circular bearing on said frame spaced from said shaft but concentric therewith to receive the offset portion of said cutter-bar to form a pivotal connection 30 between said cutter-bar and said frame, means for supporting said bearing and said shaft together with said offset portion and said cutter-bar in various lateral positions transversely of said frame, and 35 locking mechanism for rigidly holding the cutter-bar in adjusted angular position and from turning in either direction from such adjusted position relatively to said offset portion.

112. In a mining machine, the combination with a track-mounted main frame, of a cutter-frame comprising a boom pivoted to said main frame for vertical and lateral movements relatively thereto, a cutter-bar pivoted to said boom at the end thereof opposite the connection between said boom and said main frame, for lateral movement relatively to said boom while said cutter-bar and said boom are supported entirely by said 50 main frame, a shaft extending longitudinally of said boom and journaled thereon, a chain-cutter carried by said cutter-bar, gearing for driving said chain-cutter from said shaft, and a motor on said main frame 55 for driving said shaft, said main frame together with the parts mounted thereon being bodily movable while said chain-cutter is being driven.

113. In a mining and loading machine, a 60 main frame, a motor on said frame, a gear having a vertical axis driven by said motor, a pivot block arranged to turn laterally about the upright axis of said gear, a shaft journaled in said pivot block and having a 65 pinion thereon arranged to mesh with said

gear and to be driven thereby at various positions of lateral adjustment about the axis of said gear, a boom pivotally mounted on said pivot block to swing vertically relative thereto, a shaft journaled on said boom, a 70 clutch for connecting said last-mentioned shaft with the shaft journaled in said pivot block when said boom is in one position and for disconnecting said shafts to permit vertical movement of said boom, and a cutter pivotally mounted at the end of said boom and arranged to be driven by said shafts when said shafts are clutched to one another. 75

114. In a mining and loading machine, a main frame, a boom having one end thereof pivotally mounted at one end of said main frame and arranged to swing vertically and laterally relative thereto, a motor on said frame, a shaft journaled on said boom, gearing for driving said shaft from said motor 80 independently of the lateral position of said boom relative to said main frame, a clutch for disconnecting said shaft to permit vertical movement of said boom relative to said main frame, a cutter-bar pivotally mounted 85 on said boom at the end thereof opposite the connection between said boom and said main frame, and a cutter-chain mounted on said bar and driven by the shaft journaled on said boom. 90

115. In a mining machine, the combination with a supporting frame, of kerf-cutting mechanism mounted thereon, wheels for supporting said frame for travel along a mine track, a supplemental supporting 100 frame, means for accurately guiding the main frame along said supplemental frame to secure a plane feeding movement of said kerf-cutter, means for shifting the weight of the supporting frame from the front wheels 105 of the said supplemental frame, and means for moving the supporting frame together with said kerf-cutting mechanism along said supplemental frame to effect feeding of said kerf-cutting mechanism. 110

116. In a mining machine, the combination with a supporting frame, of a pair of truck wheels for supporting the rear portion of said frame for travel on the mine track, a second pair of truck wheels for supporting the forward portion of said frame for travel on the mine track, and means for supporting the forward portion of said frame while said second-named truck wheels run off the forward end of the mine track. 115

117. In a mining machine, the combination with a supporting frame having truck wheels adapted to travel on an ordinary mine track, of an extensible supplemental track adapted to extend in advance of said mine track, and 120 means for shifting the weight of said supporting frame onto said supplemental frame for movement in advance of the forward end of said mine track. 125

118. A mining and loading machine com- 130

prising a main frame having cutting mechanism connected therewith, means for shifting said frame for feeding said cutting mechanism into the material to be mined, a supporting frame connected with said main frame and movable vertically relative thereto, means for slidably supporting said main frame on said supporting frame when said supporting frame is in a lowered position relative to said main frame, and truck wheels for supporting said main frame on an ordinary mine track when said supporting frame is in an elevated position relative to said main frame.

119. In a mining machine, the combination with a main frame, of a supplemental frame having longitudinally extending spaced-apart guideways, shoes movable along said guideways, means for vertically shifting said shoes relatively to said main frame to shift the weight of the latter onto and off of said guideways, a plane chain kerf-cutter mounted on said main frame to move bodily therewith in position to cut a kerf in a plane parallel to said guideways, and means for operating said kerf-cutter including the feed thereof by movement of said main frame along said guideways when the weight of said main frame is carried by said guideways.

120. In a mining and loading machine, the combination with a track-mounted main frame, of a boom mounted on said main frame to move bodily therewith while carried wholly thereby, said boom having one end thereof pivotally connected with said main frame for vertical and lateral movement relatively thereto, a guide for supporting the opposite end of said boom on said main frame while the latter is free to travel along a mine track, means for adjusting said guide vertically relative to said main frame to raise and lower the end of said boom, means for shifting said boom laterally on said guide, and cutting mechanism carried by said boom.

121. In a mining and loading machine, the combination with a main frame, of wheels for supporting said main frame on a mine track, a boom having one end thereof pivotally mounted on said main frame adjacent one end thereof, a slide block carried by said main frame adjacent the other end thereof and having sliding engagement with said boom, worm gearing for adjusting said slide block vertically relatively to said main frame and for holding said block in its various positions of adjustment, means for shifting said boom laterally on said slide block while being supported entirely by said main frame and while the latter is free to roll along said mine track, and cutting mechanism carried by said boom.

122. A mining machine comprising a main frame, truck wheels for supporting said main frame, a movable supporting frame for said main frame, means for shifting the weight of said main frame alternately from said truck wheels to said supporting frame, means for

feeding said main frame along said supporting frame, and a cutter connected with said main frame to be moved thereby into material to be mined during the feeding of said main frame along said supporting frame.

70

123. In a mining machine, a main frame, a supporting frame for said main frame, truck wheels for supporting said main frame, means for shifting said supporting frame vertically relatively to said main frame to transfer the weight of said main frame to and from said truck wheels and said supporting frame, gearing for shifting said supporting frame relative to said main frame, and means for driving said gearing at different rates of speed and so in opposite directions.

75

124. In a mining machine, a main frame having a motor thereon, a gear having an upright axis journaled on said frame and driven by said motor, a boom pivotally mounted on said main frame to swing vertically and laterally, a shaft on said boom arranged to be driven by said gear, a cutter carried by said boom, mechanism for propelling said main frame in a mine chamber, gearing for operating said propelling mechanism from said first-mentioned gear, and mechanism also driven by said first-mentioned gear for shifting said said boom about its pivotal support.

90

125. In a mining and loading machine, the combination with a main frame, of a boom pivotally mounted on said main frame, kerf-cutting mechanism carried by said boom, means for driving said kerf-cutting mechanism, a drum carried by said frame, means for rotating said drum at different speeds in opposite directions, and cables arranged to be wound on said drum and connected to said boom to swing the latter when said drum is rotated.

100

126. In a mining machine, a frame having a boom pivoted thereon for lateral movement, a cutter pivotally connected with the end of said boom, means for locking said cutter against pivotal movement on said boom, and means for swinging said boom and cutter at different speeds in opposite directions about the pivotal connection of said boom with said frame.

105

127. A mining machine comprising a frame, a boom having its rear end portion pivotally connected to the rear end portion of said frame for swinging movement laterally of the forward portion of the frame, cutting mechanism pivoted to the forward end of said boom for swinging movement laterally relatively to said boom, means for locking said cutting mechanism in adjusted position relative to said boom, and means for swinging the boom and cutting mechanism at different speeds about its pivotal connection to the rear portion of said frame.

110

128. A mining machine comprising a main frame, a boom having one end thereof pivotally mounted on said main frame adjacent one

115

120

125

130

end of said main frame, a cutter pivotally carried on the end of said boom opposite the connection between said boom and main frame, means for locking said cutter against movement upon its pivot, a drum on said main frame, means for driving said drum at a comparatively slow rate of speed in one direction and at a higher rate of speed in another direction, a cable connected with said drum and boom and arranged to swing said boom in one direction when said drum is being slowly driven, and a second cable connecting said boom and drum and arranged to swing said boom in the opposite direction when said drum is driven at its higher rate of speed.

129. In a mining machine, a frame having a boom thereon, a cutter pivotally connected with the end of said boom, means for locking said cutter against movement relative to said boom, a drum having cables arranged to be wound thereon to swing said boom in opposite directions, a gearing for driving said drum, said gearing having one train of gears for rotating said drum at one speed in one direction and another train of gears for rotating said drum at another speed in the opposite direction, and a clutch for selectively connecting said trains of gears with said drum.

130. In a mining machine, a motor, a main drive gear arranged to be rotated by said motor, a second gear meshing with said main drive gear, a third gear also meshing with said main drive gear, two sets of propelling mechanism for said machine, means for selectively connecting said propelling mechanism with said second gear, a boom on said machine having a cutter connected therewith, a drum having cables wound thereon for swinging said boom, and gearing driven by said third gear for rotating said boom at different speeds in opposite directions.

131. In a mining machine, a main frame, a boom pivotally mounted on said main frame, a cutter carried by said boom, truck wheels for supporting said main frame, a movable supporting frame for said main frame, means for selectively shifting the weight of said main frame to and from said truck wheels and supporting frame, means for driving said truck wheels to propel said main frame along a track, means for moving said main frame along said supporting frame, a drum having cables arranged to be wound thereon in opposite directions for swinging said boom upon its pivotal connection with said main frame, a cutter carried by said boom, a motor on said main frame, and gearing driven by said motor for operating said drum, cutter, and propulsion mechanism.

132. In a mining machine, the combination with a main frame, of an elongated boom mounted on said main frame to move bodily therewith while carried wholly therewith, a pivotal connection between said elongated

boom and said main frame to permit said boom to extend longitudinally of said frame in a general horizontal direction and for swinging movement laterally relatively to said main frame, an arcuate guide for said boom for its lateral swinging movements on said main frame, an elongated chain kerf-cutter carried by said boom to swing bodily therewith, and means for swinging said boom laterally together with said kerf-cutter to feed the latter transversely of itself.

133. In a mining and loading machine, the combination with a supporting frame adapted to be moved about in a mine chamber, of a boom having the rear end thereof pivotally connected to the rear portion of said supporting frame while the forward portion of said boom is supported by the forward portion of said supporting frame, a cutter pivotally mounted on said boom adjacent the forward end of said supporting frame, means for holding said cutter in a predetermined angular relation with said boom, and means for swinging said boom and said cutter about the pivotal connection of said boom with said frame adjacent the rear end of said frame while said boom and cutter are supported by the forward end of said supporting frame.

134. A mining and loading machine comprising a unitary main frame, a boom having the rear end thereof pivotally connected with said main frame adjacent the rear end of said main frame, a cutter pivotally carried by the forward end of said boom adjacent the forward end of said main frame, means for raising and lowering said boom to bring said cutter into and out of operative position adjacent the floor of a mine chamber, means for locking said cutter relative to said boom, and means for swinging said boom and cutter laterally relatively to said main frame during a cutting operation.

135. A mining and loading machine comprising a unitary main frame, means for supporting said main frame for movement along a mine track, a boom pivotally connected with said main frame adjacent the rear end thereof, a cutter pivotally mounted on said boom adjacent the forward end of said main frame and arranged to be moved by said boom into a position adjacent the floor of said mine below said mine track, means for holding said cutter against pivotal movement on said boom, and means for swinging said boom and cutter laterally relatively to said main frame about the pivotal connection between said boom and main frame at the rear end of said main frame.

136. In a mining machine, the combination with a main frame, of truck wheels for supporting said main frame to travel on an ordinary mine track, a supplemental frame carried by said main frame for movement bodily therewith during transportation along

5 said mine track, means for moving said supplemental frame into position to support said main frame, and means for moving said main frame along said supplemental frame independently of said truck wheels and while said main frame is supported by said supplemental frame.

10 137. In a mining machine, the combination with a main frame, of truck wheels for supporting said main frame to travel on a mine track during transportation, means for driving said truck wheels to propel said main frame along said mine track for transportation, a supplemental frame connected to said main frame to move bodily therewith during transportation, and means co-operating with said supplemental frame for propelling said main frame along said supplemental frame independently of said truck wheels.

15 138. In a mining machine, the combination with a main frame, of cutting mechanism carried by said main frame, truck wheels for supporting said main frame on an ordinary mine track, means for operating said truck wheels to propel the machine along such mine track, a supplemental frame movably connected to said main frame for transportation therewith along said mine track, means for driving said cutting mechanism, and means for moving said main frame along said supplemental frame independently of said truck wheels to secure feed of said cutting mechanism independently of movement of said truck wheels along said mine track.

20 139. In a mining machine, a main frame, a cutter carried by said main frame, truck wheels for supporting said main frame, means for operating said truck wheels to propel said machine along a mine track, a supplemental supporting frame movably connected with said main frame, means for shifting the weight of said main frame alternately to and from said truck wheels and said supplemental supporting frame, and means co-operating with said supplemental supporting frame for moving said machine along said supplemental frame to feed said cutter into the material to be mined.

25 140. In a mining and loading machine, a main frame, truck wheels for supporting said main frame, a supplemental supporting frame movably connected with said main frame, a motor carried by said main frame, conveyor mechanism for loading material disconnected by said cutter, means for shifting the weight of said main frame alternately to and from said truck wheels and said supporting frame, and means for engaging said supplemental frame when the weight of said main frame is supported thereby to move said main frame along said supplemental frame to feed said cutter relative to the material to be mined.

30 141. In a mining machine, the combination

65 with a main frame, of an elongated supplemental frame pivotally connected to the rear portion of said main frame in position to swing laterally over the front portion of said main frame, elongated cutting mechanism extending outwardly from the outer end of said supplemental frame to swing with the latter on a long radius, means for swinging said supplemental frame on its pivotal connection to said main frame to move said cutting mechanism in an arc, and means for adjusting the angular position of said cutting mechanism relative to said supplemental frame.

70 142. In a mining machine, the combination with a main frame, of means for supporting said main frame to travel along a mine track, of an elongated cutter-frame, a traveling chain-cutter on said cutter-frame, a supplemental frame pivotally connected to the rear portion of said main frame for swinging movement relatively thereto on an upright axis, means for pivotally connecting the rear end of said cutter frame to the forward end of said supplemental frame for arcuate adjustment relatively thereto, means for securing said cutter-frame relative to said supplemental frame, and means for swinging said supplemental frame together with said cutter-frame on said axis at the rear portion of said main frame to effect feeding movement of said chain-cutter in an approximate- 75 ly horizontal plane.

80 143. In a mining machine, the combination with a main frame, of a supplemental frame pivotally connected to said main frame to swing on an upright axis at the rear portion of said main frame, an elongated cutter-bar, a chain-cutter mounted on said cutter-bar, a pivotal connection between said cutter-bar and said supplemental frame to permit adjustment of said cutter-bar relative to said supplemental frame independently of the pivotal connection between said supplemental frame and said main frame, and means for effecting swinging feeding movement on said axis at the rear portion of said main frame to secure the cutting of a kerf in an upright mine wall in advance of the path of travel of said main frame.

85 144. In a mining machine, the combination with a unitary main frame, of an elongated boom pivotally connected at one end to the rear portion of said main frame to move bodily therewith while carried wholly thereby and for lateral swinging movement relatively to said main frame while extending longitudinally thereof in a general horizontal direction, an arcuate guide at the forward end of said main frame for supporting and guiding the forward end of said boom, an elongated chain kerf-cutter carried by said boom and extending outwardly therefrom in advance of said main frame, and means for swinging said boom laterally together with

said elongated kerf-cutter to secure lateral swinging and feeding movement of said kerf-cutter along an arc having a comparatively long radius.

- 5 145. In a mining machine, the combination with a supporting frame for forming a unitary structure, of an elongated supplemental frame pivotally connected at its rear end portion to the rear end portion of said supporting frame in position to swing laterally along the front portion of said supporting frame, an elongated chain kerf-cutter mounted on said supplemental frame for pivotal adjustment relatively thereto and to extend 10 forwardly from the forward end of said supplemental frame, means for holding said elongated chain kerf-cutter in adjusted position relative to said supplemental frame, means for swinging said supplemental frame 15 together with said kerf-cutter on its pivotal connection at the rear end portion of said supporting frame to move said kerf-cutter along an arc having a comparatively long radius, and means for driving said kerf-cutter 20 during the swinging movement thereof.

146. In a mining machine, the combination with a main frame forming a unitary structure, of wheels for supporting said frame to travel on a mine track, an elongated supplemental frame pivotally connected to the rear portion of said main frame and extending forwardly in a general horizontal direction, a gooseneck extension to swing with the latter on a long radius and in position to cut a 25 kerf in the plane of the floor of the mine chamber, means for swinging said supplemental frame on its pivotal connection to said main frame to feed said kerf-cutting mechanism in an arc on such long radius, 30 means for driving said kerf-cutting mechanism, and means for propelling said main frame along the track while supporting said supplemental frame and said cutting mechanism to move bodily with said main frame.

147. In a mining machine, the combination with a portable main frame, of an elongated supplemental frame pivotally connected to the rear portion of said main frame, an elongated kerf-cutter adjustably connected to the forward end of said supplemental frame, means for holding said elongated kerf-cutter in adjusted angular relation to said supplemental frame, means for moving said main frame to secure rectilinear feeding movement of said kerf-cutter, and means for swinging said supplemental frame to secure arcuate movement of said kerf-cutter.

148. In a mining machine, the combination with a wheel-mounted main frame adapted to travel on a mine track laid to extend to a position adjacent a mine heading, of a supplemental frame pivotally connected to the rear portion of said main frame and extending longitudinally along the top thereof, a gooseneck downward extension from the for-

ward end of said supplemental frame, an elongated kerf-cutter connected to the bottom of said gooseneck extension in position to cut a kerf in the plane of the floor of the mine chamber, means for moving said main frame together with said supplemental frame along said track to secure rectilinear movement of said elongated kerf-cutter in the plane of the floor while the latter extends angularly from one side of the track toward the mine heading, and means for swinging said supplemental frame laterally to secure arcuate feeding movement of said kerf-cutter in the plane of the floor.

149. In a mining machine, the combination with a wheel-supported main frame adapted to travel on a mine track, of an elongated supplemental frame pivotally connected to the rear portion of said main frame and mounted thereon to swing laterally along the front portion of said main frame, an elongated kerf-cutter connected to the outer end of said supplemental frame for angular adjustment relative thereto, means for holding the kerf-cutter in adjusted angular position relative to said supplemental frame, means for moving said kerf-cutter, means for propelling said main frame together with said supplemental frame to secure rectilinear feeding movement to said kerf-cutter into the coal wall, and means for swinging the supplemental frame laterally to secure arcuate feeding movement to said kerf-cutter on a long radius so that the inner end of said kerf will approach more nearly a straight line at right angles to the path of travel of the main frame along said track.

150. In a mining machine, the combination with a portable main frame, of an elongated supplemental frame pivotally connected to the rear portion of said main frame and extending in a general horizontal direction along the upper portion of said main frame toward the forward end thereof, a gooseneck downward extension from the forward end of said supplemental frame, an elongated chain kerf-cutter connected to said extension in position to cut a kerf at the base of the mine wall, means for holding said supplemental frame and said kerf-cutter in adjusted angular relation to said main frame, and means for moving said main frame to secure rectilinear feeding movement of said kerf-cutter.

151. In a mining machine, the combination with a supporting frame, of a plane chain kerf-cutter mounted thereon, truck wheels for said frame for movement along an ordinary mine track, a self-contained supplemental track adapted to support said main frame, and means for operating said kerf-cutter including rectilinear feed thereof along said supplemental track in advance of the mine track and independently of the guidance of said truck wheels along said mine track.

152. In a mining machine, the combination with a wheel-supported main frame adapted to travel along an ordinary track, of a supplemental track adapted to support said main frame, elongated chain kerf-cutting mechanism, and means for operating said kerf-cutting mechanism including rectilinear movement thereof along said supplemental track in advance of said mine track and independently of guidance along said ordinary mine track.

153. In a mining machine, the combination with a wheeled-supported main frame adapted to travel on a mine track, of a supplemental frame pivoted to the rear portion thereof, an elongated chain kerf-cutter suspended from the forward end of said supplemental frame in position to cut at the level of the mine floor on which the mine track is laid, means for guiding the forward end of said supplemental frame for arcuate movement laterally of said main frame and to support said kerf-cutter in position for movement along either side of the mine track while at the level of the floor on which the track is laid, means for moving said main frame rectilinearly parallel to the track to secure rectilinear movement of the kerf-cutter at both sides of the track, and means for swinging said kerf-cutter to secure arcuate feeding movement along the base of an upright mine wall across the forward end of said track.

154. In a mining machine, the combination with a portable frame, of a boom pivotally connected to the rear portion of said frame to swing vertically and laterally relatively to said frame, an elongated kerf-cutter adapted to be located in an undercutting position, and a goose-neck connection between the forward end of said boom and the rear end of said kerf-cutter.

155. In a mining machine, the combination with a supporting frame, of a boom pivoted thereto for lateral movement relatively thereto, a kerf-cutter pivotally connected to the free end of said boom, means for locking said kerf-cutter against pivotal movement relatively to said boom, and means for swinging said boom to effect slow feeding movement of said cutter in one direction and for effecting the quick return movement of said boom to restore said cutter to initial position about the pivotal connection of the boom to said frame.

156. In a mining machine, the combination with a supporting frame, of a supplemental frame mounted on said supporting frame for pivotal movement on an upright axis and a horizontal axis, an elongated cutting tool, a neck connecting said elongated cutting tool to said supplemental frame for lateral adjustment relative to said supplemental frame on an upright axis, and means for effecting adjustment in elevation of the said neck and said elongated cutting tool by swinging said

supplemental frame on said horizontal axis.

157. In a mining machine, the combination with a main frame, of a supplemental frame pivotally connected to said main frame to swing on an upright axis and also a horizontal axis, an elongated cutting tool, a depending neck connecting said supplemental frame to said elongated cutting tool, and means for adjusting the elevation of said neck on said horizontal axis to let the cutting tool down to the floor level when cutting operations are to be performed and to hold said cutting tool in elevated position during transportation.

158. In a mining machine, the combination with a supporting frame, of a supplemental frame pivotally connected to the rear portion of said supporting frame for lateral swinging movements on an upright axis, an elongated cutting tool, a depending neck connection between the forward end of said supplemental frame and said cutting tool for mounting the latter on said supporting frame, and mechanism for swinging said supplemental frame by its neck to effect lateral feeding movement of said cutting tool on said upright axis.

159. In a mining machine, the combination with a supporting frame, of a body member pivoted thereto for up and down movement and for lateral movement relatively to said supporting frame, an elongated cutting tool, a depending neck connecting the forward end of said body member and said cutting tool, means applied to said neck for adjusting the elevation of said cutting tool, and means also applied to said neck for swinging the said body member laterally to effect lateral swinging movement of said cutting tool.

160. In a mining machine, the combination with a supporting frame, of a body member mounted on said frame for lateral movement relatively thereto on an upright axis, an elongated cutting tool, a neck connecting said elongated cutting tool to the forward end of said body member, a journal bearing between said neck and the forward end of said body member to permit lateral swinging adjustment of said cutting tool relative to said body member, means for locking said neck and cutting tool in adjusted position relative to said body member, and means connected to the forward end of said body member adjacent said neck for swinging said cutting tool together with said neck and said body member laterally on said upright axis relatively to said supporting frame while the latter remains stationary.

161. In a mining machine, the combination with a frame, of a supplemental frame pivoted to said main frame for vertical and lateral movements relatively thereto, a cutting element pivoted to said supplemental frame at the end thereof opposite the connection between said supplemental frame and said main frame, for lateral movement rela-

tively to said supplemental frame while the latter and said cutting element are supported entirely by said main frame, a shaft extending longitudinally of said supplemental frame and journaled thereon, power transmission mechanism between said shaft and said cutting element, and mechanism connected between said main and supplemental frames for effecting swinging feeding movement of said cutting element.

162. In a mining machine, the combination with a portable main frame, of a supplemental frame pivotally connected to said main frame at the rear portion thereof for 15 swinging movement relatively thereto on an upright axis, said supplemental frame extending in a general horizontal direction along the top of said main frame and toward the forward end thereof, an elongated cutting element connected to the forward end of said supplemental frame, an arcuate guide on said main frame for the forward end of said supplemental frame, means for holding said cutting element in adjusted angular relation 20 to said main and supplemental frames, and means for moving said main frame to secure rectilinear feeding movement of said cutting element in its adjusted position.

163. In mining apparatus, the combination 25 with cutter supporting and directing means movable on a trackway into operative position at right angles of a working face, of cutting mechanism, a supplemental frame guided arcuately on said supporting means and 30 pivoted at its rear end thereto and comprising a depending neck for supporting said cutting mechanism in position to cut a path for itself when presented to said working face, and power driven means for operating 35 said cutting mechanism including the feed thereof longitudinally and angularly relative to said directing means to insert in the working face a kerf of greater width than the effective length of the cutting mechanism.

40 164. In mining apparatus, the combination 45 with wheeled guiding means, of cutting mechanism, means pivoted at its rear end to said guiding means and comprising a depending neck for supporting said cutting 50 mechanism on said guiding means with the free end of said cutting mechanism at an acute angle to said guiding means, and power driven means for moving the cutting mechanism longitudinally into the face when so disposed and thereafter successively swinging the same and withdrawing the same from the face by reverse longitudinal movement.

60 165. In mining apparatus, the combination 65 with guiding means parallel to and movable on a trackway and disposed thereon at right angles to the working face, of a kerf-cutter, means pivoted at its rear end to said guiding means and comprising a depending neck for supporting said kerf-cutter on said

guiding means for movement relatively thereto, and power driven means to effect insertion of said kerf-cutter into the working face by longitudinal movements and also angular movements relative to said guiding means.

166. A mining machine comprising guiding means located on the machine for transportation bodily therewith and adapted to occupy a stationary position at the bottom of the machine, a supporting frame connected to 70 said guiding means for movement along the latter, cutting mechanism mounted on said supporting frame for swinging movement relatively thereto in advance of said guiding means, means for moving said supporting frame along said guiding means to effect rectilinear feeding movement of said cutting mechanism, and means for swinging said cutting mechanism outwardly from said guiding means and in advance thereof relatively to 75 said supporting frame to effect arcuate feeding movement of said cutting mechanism in advance of said guiding means.

167. In mining apparatus, the combination 80 with a main frame movable on a trackway, of a supplemental frame pivoted at its rear end to said main frame for swinging movement laterally on an upright axis, a depending neck on said supplemental frame, cutting mechanism connected to said neck, 85 and means for effecting the operation of said cutting mechanism to cut a horizontal kerf in a face parallel to the trackway, an arcuate kerf in said face in front of the trackway, and a horizontal kerf parallel to said first-named horizontal kerf.

168. In a mining machine, the combination 90 with a wheel-supported main frame adapted to travel on a mine track, of a supplemental frame movable laterally on said main frame, 95 an elongated cutting element, a gooseneck for supporting said cutting element to cut a kerf in the plane of the floor in advance of the mine track, an upright journal bearing on said supplemental frame for said gooseneck, locking mechanism for holding the cutting element in adjusted angular relation to said supplemental frame, and means for moving said supplemental frame laterally to 100 secure feeding movement of said cutting element to cut a kerf in the plane of the floor on which the track is laid.

169. In a mining machine, the combination 110 with a supporting frame, of an elongated supplemental frame pivoted to the rear 115 portion of said supporting frame to swing laterally on the upright axis relatively to said supporting frame, said elongated supplemental frame extending along the upper portion of said supporting frame in a general horizontal direction to the forward end thereof, an elongated cutting element connected to the forward end of said supplemental frame.

- tal frame to extend forwardly therefrom and move bodily therewith, means at the forward portion of said supporting frame for guiding said supplemental frame for lateral movement on said supporting frame, means for driving said cutting element, and means for swinging said cutting element to secure arcuate feeding movement thereof on a long radius equal approximately to the length of said supplemental frame plus the length of 10 said cutting element.
- 5 In testimony whereof I have signed my name to this specification.

EDMUND C. MORGAN.
